Application April 7, 1939, Serial No. 266,612

35 Claims. (Cl. 244—90)

This invention relates to certain improvements in airplanes, and the nature and objects of the invention will be readily recognized and understood by those skilled in the aeronautical and related arts, in the light of the following explanation and detailed description of the accompanying drawings, illustrating what I now believe to be the preferred embodiments or aerodynamical and mechanical expressions of my invention, from among various other embodiments, arrangements, combinations and constructions, of which the invention is capable within the broad spirit and scope thereof.

With the standard systems of lateral or roll control employing the conventional types of ailerons forming trailing portions of opposite wings, respectively, of an airplane, in which systems the ailerons are interconnected, and simultaneously differentially deflected vertically, in opposite directions, for lateral control, it is not practically possible to use full span wing flaps of the trailing under surface types, due primarily, to the fact that with such full span flaps in their normal raised, inactive positions, the necessary downward deflection of an aileron in the control operation of the conventional differentially actuated type of aileron control system is prevented. A type of lateral or roll control surface or aileron that will permit the use of a full span wing flap is exemplified by the so-called up-only aileron. Such type of aileron forms a part of the trailing upper surface only of a wing and is mounted for upward deflection only from neutral position to control positions and may, therefore, be positioned above a full span wing flap that forms a portion of the under surface only of the wing below such an upper surface aileron.

With such up-only ailerons mounted on opposite wings of an airplane, an aileron actuating or controlling system is provided, of a design and arrangement such that upon upward deflection of the aileron on one wing, the opposite wing aileron is maintained inactive and at rest in its normal neutral position against deflection, and the rolling moment for lateral control is obtained primarily as a result of the upwardly deflected aileron. Ailerons of the up-only type provide an effective lateral or roll control means for an airplane and have the advantage of permitting the use of full span wing flaps to thereby gain the increased flap performance possible with full span flaps, as against the performance of the partial span flap necessitated by the conventional type of aileron system. However, ex-

perimental use of various designs of the up-only aileron has indicated that the up-only type of aileron possesses certain inherent disadvantages which, until eliminated or overcome, render such type of aileron unsatisfactory and impractical for use.

One of the most serious disadvantages thus indicated is that the operation of an up-only aileron, acting alone and designed to effectively replace two differentially acting ailerons, involves a substantial increase in control forces or aileron hinge moments. A brief comparison of the two systems should serve to show how this is brought about.

15 First, it should be recognized that under normal conditions the air flow rearward along the under surface of a wing is more effective as an agent acting upon a downwardly-deflected aileron than is the air flow rearward over the upper surface of a wing as an agent acting upon an upwardly-deflected aileron. Largely for this reason it is customary to work out the aileron linkage in such a way that the up-acting aileron of a differentially operated aileron system swings upward for full control through a relatively large angular deflection of 25 degrees perhaps, while the opposite and down-acting aileron swings downward through only 15 degrees. It is reasonable to conclude, therefore, that an aileron 20 of the up-only type, acting singly to replace the two ailerons of the differentially operated system, and acted upon solely by the air flow above the upper surface of the wing, will need to be deflected through at least as many degrees as 25 would the up-acting aileron of the differentially operated system; and experimental data to date, covering various types of up-only ailerons other than that of my design, indicate that such up-only ailerons probably would need to be given a 30 much greater angular displacement in order to prove suitably effective. An increase in angular displacement is certain to be attended by an increase in control forces.

Second, an up-only aileron, acting singly to 35 replace the two ailerons of a differentially operated system, must have approximately the same effective surface area as that of the two ailerons it replaces. And, due to the character of the air flow above the upper surface of the 40 wing, it is at least possible that an increase in effective surface area will be demanded. Increase in surface area indicates an increase in control forces.

Third, the ailerons of differentially operated 45 aileron control systems in common use today are

aerodynamically balanced; and the aerodynamic balance is most effective as a means of reducing control forces. The up-only ailerons heretofore experimentally tested have not been designed to make an aerodynamic balance, if any, fully operative throughout the operating control range of the aileron—especially with an under-surface flap in its neutral, retracted position, which is the natural position for such a flap under normal flight conditions.

In comparison with the control forces experienced in the operation of a differentially operated aileron control system, it is to be expected that an up-only aileron, of large surface area, and perhaps deflected to high-angle positions for full control, must involve a substantial increase in control forces when operated without an effective aerodynamic balance.

My present invention is directed toward the reduction of the excessive control forces that must be overcome in the operation of an up-only aileron while maintaining effective lateral or roll control from such aileron; and, in accordance with the principles of my invention, I reduce the control forces encountered in the operation of the up-only aileron to its upwardly deflected control positions, by aerodynamically balancing such type of aileron in such a manner as to develop forces acting about the aileron axis of deflection in a direction to materially aid in the upward deflection of the aileron so as to thereby reduce the operating forces required to upwardly deflect the aileron to its control position.

The feature of the invention that provides for aerodynamic balancing of an up-only aileron is carried out by mounting the aileron for vertical rotation and angular deflection relative to the wing, about a balance hinge axis, located intermediate the leading and trailing edges of the aileron to thereby form the portion of the aileron that extends forwardly of said axis, as an aerodynamic balance, to be reacted upon by the flow of air rearwardly over the upper surface of the wing to develop forces acting about the balance axis in a direction to aid upward deflection of the aileron. With the up-only aileron positioned as a portion of the trailing upper surface of a wing, with a portion of the wing structure, such as a wing flap, there beneath, if the aileron is rotated about its balance axis to upwardly deflect the trailing portion thereof, then the leading portion or aerodynamic balance is deflected downwardly into a position in which the leading edge portion thereof, at least, will be blanketed from the air flow and the effectiveness of the balance and the balancing forces developed thereby, materially reduced, particularly throughout the range of maximum deflection of the aileron.

In order to make the balance portion of the aileron fully effective to obtain a maximum balancing force therefrom, my invention provides, as a further feature and characteristic thereof, the mounting of the aileron for bodily movement upwardly about a hinge axis spaced forwardly of and remote from the aileron so that in the control operation of the aileron it is initially moved from neutral position to a raised position fully exposed in and to the air flow over the upper surface of a wing and angularly deflected relative to the wing. The upwardly raised position of the aileron, relative to structure of the wing, is then such that the aileron may be upwardly deflected about the balance axis to its maximum control position with the balance portion of the aileron forward of the balance axis exposed to

and acted upon by the rearward air flow over the wing throughout the range of upward deflection, with the development of increasing balancing forces as the angle of upward deflection of the aileron is increased. Thus, an up-only aileron in accordance with my invention, may be mounted to have movement for progressive angular displacement from neutral position to maximum upwardly deflected control position about two separate axes, which movement consists initially in bodily raising the aileron about a forward remote hinge axis to a position raised into the air flow over the wing, and then rotating the aileron about a balance axis intermediate the leading and trailing edges of the aileron when the latter is in this raised position to upwardly deflected control positions. The rotation and upward deflection of the aileron about its balance axis may be initiated after the aileron has reached maximum raised position about the remote hinge axis, or may be initiated prior thereto and during upward movement of the aileron about such hinge axis.

In the conventional aileron control system, where the opposite ailerons are interconnected and simultaneously vertically deflected in opposite directions, the hinge moments of these opposite ailerons are always balanced, and, therefore, with the ailerons in neutral position, the hinge moments of the individual ailerons are of no consequence, as there is a condition of static balance and the system may be actuated through neutral with a smooth, uninterrupted movement of the control system, and without any abnormal or unusual feel being experienced by the pilot during such operation. However, in a lateral or roll control system of the up-only aileron type, there is an inherent condition of static unbalance encountered. This condition of static unbalance is caused by the fact that with the up-only aileron system, only one aileron of the opposite ailerons is upwardly deflected and in motion at any given time, so that, for example, the operation of such a system to lower an upwardly deflected aileron to neutral position, and then raise the opposite aileron from its at-rest, neutral position, it is necessary to first lower the upwardly deflected aileron into its at-rest position, and then to pick up the opposite aileron from its position at rest in neutral for upward deflection thereof. The inertia loads set up by stopping one aileron and then picking up and setting the opposite aileron in motion from its at-rest position, are transmitted into the system and produce an abnormal, disturbing and unsatisfactory feel to the pilot in operating the system back and forth through neutral position. In actual flight operation and use of the up-only type of aileron system, this abnormal feel in the control, due to static unbalance, is sufficiently objectionable and disconcerting to the pilot as to bring this type of lateral or roll control system into disfavor and tend to prevent its practical adoption, notwithstanding certain definite advantages of the type such as referred to hereinbefore.

My present invention provides for the elimination or substantial reduction of this condition of static unbalance in an up-only aileron control system, so that in the operation of such type of system, the abnormal and objectionable feel encountered in the operation of the controls is done away with and a normal smooth operation of the control system is obtained throughout its operating range, including the neutral control positions.

This condition of static unbalance, following the

principles of my invention, is substantially eliminated by the application to each aileron of a force acting in a direction to raise the aileron from its neutral, at-rest, position, and of such a magnitude relative to the other forces acting in the control system, that as the system is operated through neutral to pick up and upwardly deflect the at-rest aileron, this raising force acts ahead of the raising force applied to the aileron by the system. Therefore, as the control system passes through neutral and movement thereof is continued to upwardly deflect the at-rest aileron, such aileron has already, in effect, been picked up and is being raised by said force so that the control system is relieved of the inertia load of picking up an at-rest aileron and a continuous smooth operation of the control system results with no abnormal or unbalanced loads imposed on the system to develop disturbing and unsatisfactory control system operating feel. Such applied force acts to, in effect, establish conditions in the system corresponding or equivalent to static balance, so that compensation of the conditions inherent in the up-only aileron type of control system, causing static unbalance, is obtained, and the abnormal and unsatisfactory feel to the pilot as the system is operated through the neutral position caused by static unbalance, is eliminated.

One of the primary requisites for lateral or roll control systems is that there be no appreciable lag between the start of the control surface movement, and the start of the resulting rolling motion, and that there should be no appreciable lag or time lapse between the movement of the pilot's control and the start of the control surface movement. Another requisite is that the operation of the control system by the pilot for a control operation should be carried out as a single smooth and continuous movement from the start of the control operation to the conclusion thereof, and preferably that the control forces on the system should progressively increase as an aileron is displaced to maximum control position. With the up-only aileron of the type and design of, and mounted in accordance with, my present invention, for movement about separate hinge and balance axes, respectively, spaced a considerable distance apart, it is essential that the aileron actuating or controlling means to be operated by the pilot, must be arranged and designed to provide for a single continuous movement by the pilot in making any control operation. Further, the relationship between such actuating means and an aileron must be such that the raising of the aileron about its remote hinge axis, followed by the rotation of the aileron as it is in its raised position about its balance axis, should be carried out by a single smooth continuous movement of the control system on the part of the pilot, with a minimum of lag between the initiation of the control movement by the pilot and the rolling response from the aileron. In addition to the foregoing requisites, the control operating or actuating means for the up-only type of aileron must be such as will provide for the maintenance and positive holding of one aileron in its normal neutral, at-rest position against deflection throughout the vertical deflection of the opposite aileron, between its neutral at-rest position and its upwardly deflected control position.

Another object and a feature of this invention is the provision of a design and arrangement of a practical and relatively mechanically simple

design and arrangement of actuating or controlling means for up-only ailerons of the design and mounted as hereinbefore generally referred to, by which an aileron can be moved about its remote hinge axis and its balance axis in vertically deflecting the aileron between its normal at-rest neutral position and its maximum upwardly deflected control position, with a continuous, smooth and uninterrupted movement of the pilot 10 control member for operating such means; and further, to provide such means by which the aileron opposite the aileron being deflected is positively held and maintained at rest against deflection from its normal neutral, at-rest position, during and throughout deflection of the opposite aileron by the operation of the actuating means.

A feature of one form of that mechanism of the controlling means that may be employed in carrying out the invention and through the medium of which the up-only aileron is progressively angularly displaced upwardly from its neutral position about the separate remote hinge and balance axes, respectively, resides in an arrangement of a toggle type of linkage for raising the aileron about the remote hinge axis, in combination and cooperative relation with, a form of parallel linkage for rotating the aileron about its balance axis to upwardly-deflected control positions after the aileron has been raised or partially raised by the toggle linkage, with such toggle linkage so relatively arranged and associated with the parallel linkage that the toggle linkage functions to prevent transmission to the system of the major portion of the control forces developed by upward deflection of the aileron about its balance axis through the operation of the parallel linkage, particularly in the range of high angles of aileron upward deflection.

40 A control system of the invention in one possible form thereof, is further characterized by an arrangement of actuating mechanism that includes reciprocal linkages operatively coupled with the mechanisms for upwardly deflecting the ailerons to control positions and lowering the same from such positions, by which reciprocal linkages the aileron actuating mechanisms are alternatively operated so that upon actuation of the system to upwardly deflect one aileron, the opposite aileron actuating mechanisms are maintained inactive with such opposite aileron held in its neutral position against upward deflection therefrom; the combination and cooperative association of the pilot operated reciprocal linkage and the opposite aileron actuating mechanisms being such that an aileron may be actuated to and from control positions by continuous smooth and uninterrupted actuation of the pilot-operated control member, throughout the operating range of the system.

60 This invention includes, as a further novel feature thereof, the provision of trimming tabs to the ailerons of a lateral or roll control system of the up-only aileron type; and the arrangement of such trimming tabs in the system is characterized by the fact that the trimming tabs of the opposite ailerons are independently adjustable and that such trimming tabs in functioning to attain lateral trim or balance, may be arranged to be either depressed to thereby raise the aileron by the action of the air flow at the under surface of the wing and aileron or to be upwardly deflected to depress a wing without deflecting the aileron on which mounted from its neutral at-rest position. The mounting of the trimming

tabs on the ailerons of the up-only type is further featured by the provision of independent adjusting mechanisms for such tabs, respectively, which mechanisms are so mounted on and relative to the aileron actuating means that vertical deflection of an aileron will not interfere with or materially vary the adjusted position of a tab relative to the aileron in any position to which the aileron may be deflected.

With the up-only aileron embodying the principles hereinbefore generally referred to, my invention further provides, as a feature thereof, the combination with such type of aileron of a full-span wing flap designed and mounted for lowering and raising about a remote hinge axis spaced forwardly from the leading edge thereof, and for rotation in lowered positions about a balance axis intermediate the leading and trailing edges of the flap with the portion of the flap forward of such balance axis providing an aerodynamic balance; the flap of such design and mounting being further characterized by a progressive angular displacement, relative to the wing, as the flap is bodily lowered first about the remote hinge axis, and then about the balance axis to its position of maximum angular displacement, and by the spacing of the leading edge of the flap from the under surface of the wing when the flap is lowered about the remote hinge axis to form a passage for flow of air between the wing and flap.

With the foregoing general features, characteristics and objects in view, as well as various others that will be apparent from the following explanations, my invention consists in certain novel features in design, arrangement, combination and construction of elements and parts, all as will be more fully and particularly referred to and specified hereinafter.

Referring to the drawings in which similar reference characters refer to corresponding parts and elements throughout the several figures:

Fig. 1 is a view in top plan, more or less schematic, of an airplane with a lateral or roll control system of the up-only type, embodying the principles and features of my invention, mounted and installed thereon; portions of the operating mechanisms for the right wing aileron being more or less diagrammatically shown, as associated with the pilot-controlled actuating member for the system;

Figs. 2 and 2a constitute a view in top plan of the aileron operating mechanisms constituting the lateral or roll control system for the right wing aileron, with portions of the mechanisms for operating the left wing aileron shown, all in association with the pilot-controlled operating member for the system; the mechanisms being shown in full lines in their positions with the right wing aileron in its bodily-raised position, approaching maximum bodily-raised position;

Fig. 3 is a view in vertical transverse section, taken as on the line 3-3 of Fig. 1, through the right wing aileron and the portion of the wing forward of such aileron, with the aileron actuating mechanism shown in elevation in full lines, with the aileron in its raised position approaching maximum bodily-raised position, the neutral position, and the maximum angularly-deflected position being shown in dotted lines;

Fig. 4 is a vertical transverse section, similar to the view of Fig. 3, but taken as on the line 4-4 of Fig. 1, and showing a trim tab and its adjusting mechanism mounted on and operatively associated with the right wing aileron A; the

aileron being shown in full lines in a bodily-raised position corresponding to Fig. 3, with the trim tab in an adjusted downwardly-deflected position relative to the aileron;

Fig. 5 is a vertical transverse section through a wing showing a trailing under-surface wing flap of my invention with portions of its operating mechanism, the flap being shown in full lines in its lowered position below the wing, and being also shown in dotted lines in normal raised neutral position and in its maximum downwardly-deflected position;

Fig. 6 is a detailed view in top plan of the trailing or rear end portion of a hinge arm 4 with the upper or top wall of such arm removed or broken away, and showing particularly the operative connection of such arm to the aileron and the connection of the toggle linkage and parallel linkage of the aileron actuating mechanism to such arm and to the aileron respectively; and

Fig. 7 is a detailed view in vertical transverse section through a hinge arm 4, showing the channel or U-shape of such arm in cross section and being taken as on the line 7-7 of Fig. 6.

An aerodynamical, structural and mechanical adaptation of an up-only aileron type of lateral or roll control system embodying the principles and the various features of my invention is disclosed in the accompanying drawings, as applied to an airplane having the wings thereof provided with full-span trailing under-surface wing flaps of a type and design of my invention with the up-only ailerons of the control system and such full-span flaps, positioned therebeneath in operative aerodynamic and structural relationship and association. However, an up-only aileron type of lateral control system of the invention is not limited or restricted to use in combination or association with full-span wing flaps, or flaps positioned beneath the ailerons of such system, but is equally adapted to use on and with wings without flaps or wings having partial-span flaps, with fixed wing structure beneath the ailerons of the system, all as may be desired or found expedient. The expressions of the principles and various features of the invention presented by the illustrated adaptions and embodiments thereof, are to be considered purely by way of exemplification, and not in all respects by way of limitation, such adaptions and embodiments being here primarily disclosed for the purpose of explaining and describing the basic principles and features of the invention to enable those skilled in the aeronautical art to understand the same. It is to be understood that the basic principles and the various features of the invention are capable of a variety of other aerodynamical, structural and mechanical expressions, as will be readily appreciated and understood by one skilled in the art from the following explanations of the invention and of the disclosed examples thereof.

An up-only aileron type of lateral or roll control system is disclosed in the present example, as applied to and embodied in an airplane, referring now to Fig. 1 of the drawings, that includes the body or fuselage F, a portion only of which is shown, and opposite wings W with the up-only ailerons A of the system mounted thereon as trailing portions of the upper surfaces of these wings. An operating control system is provided by which such opposite wing ailerons A may be alternately upwardly deflected, respectively, from their normal neutral at-rest posi-

tions, with the aileron opposite the one deflected, maintained in its neutral position against deflection during and throughout vertical deflection of the other aileron.

An up-only aileron A designed in accordance with the principles of my present invention may embody, referring now particularly to Fig. 3 of the drawings, a member of airfoil section, mounted and positioned on a wing W so as to form a trailing portion of the upper surface of the wing when the aileron is in its normal neutral control position, as shown by dotted lines in Fig. 3. The aileron A may be of any usual or desired type of construction such as a construction that includes the spar or beam 1, disposed spanwise thereof intermediate the leading and trailing edges, and the chordwise ribs or formers 1a, together with a skin or covering that provides the upper surface 1b and the lower surface 1c for the aileron A. It so happens in the present example, that the aileron A is formed with its under surface 1c of greater camber than the upper surface 1b which upper surface, with the aileron in neutral position, forms a portion of the trailing upper surface of the wing W, and carries out the normal airfoil section and contour of such wing upper surface, with the trailing edge of the aileron forming a portion of the trailing edge of the wing.

An aileron A is mounted on a wing W for upward movement only from its neutral position to control positions above and angularly displaced relative to the wing, and for corresponding downward movement from its control positions back to neutral, but may not, in the present example, be displaced downwardly from its normal neutral position; thus providing an aileron of the truly up-only type as distinguished from those types of up-only aileron that are mounted for a relatively slight downward displacement from normal neutral control position when the opposite aileron is upwardly deflected, although my invention is not, of course, limited to such so-called "true" up-only aileron type of the present example. Following the teachings of my invention, the aileron A is mounted for rotation about a balance axis 2 disposed spanwise of the aileron intermediate its leading and trailing edges, to thereby form and provide that portion B of the aileron A, extending forwardly of such axis, as an aerodynamic balance. Preferably, as in the example hereof, the balance axis 2 about which aileron A is to be rotated for upward angular deflection to control positions, is located spaced rearwardly from the leading edge of the aileron, a distance equal to approximately 40% of the aileron chord in order to obtain a balance portion of maximum area and chord. Obviously, my invention is in no sense limited to the particular percentage of the chord at which the balance axis is located rearwardly from the leading edge of the aileron, as this distance may be varied in accordance with the particular conditions of the design of each particular installation and more or less in accordance with the control forces or hinge moments that are to be overcome.

With the aileron A mounted for rotation about the balance axis 2, with the balance portion B extended forwardly thereof and having an appreciable chord relative to the chord of the aileron, in order to obtain the maximum balancing effect from the balance B when upwardly deflecting the aileron to control positions, it is desirable to avoid blanketing any portion of the

balance B from the air flow rearwardly over the upper surface of the wing by structure of the wing forward of the aileron. If an aileron A of the up-only type is rotated about the hinge axis 5 2 when the aileron is in normal neutral control position, not only would downward deflection of the balance B position the leading edge portion of the balance below the upper surface of the wing, but such deflection would also result in 10 structural interference between the balance and wing structure beneath the balance.

Therefore, in accordance with a further feature of my invention, the aileron A is mounted to be bodily raised about a hinge axis 3 spaced 15 a distance forwardly of and remote from the leading edge or balance portion B of the aileron, prior to upward deflection of the aileron to any appreciable degree about the balance axis 2. The location and forward spacing of the remote hinge 20 axis 3 is such that the aileron A can be swung upwardly about such axis to a position angularly deflected relative to the wing and raised a sufficient distance above the wing structure adjacent the aileron, so as to fully expose the aileron and the balance B to the air flow over the upper surface of the wing, throughout the range of vertical deflection of the aileron about the balance axis 2. This raised, angularly-deflected position of an aileron A about the remote hinge axis 3 is disclosed in full lines in Fig. 3 of the drawings; while the upwardly-deflected control position of the aileron, about the balance axis 2, is disclosed in dotted lines in Fig. 3, from which it will be readily apparent that the balance B is 35 at all times throughout vertical deflection about the balance axis 2 exposed to the air flow over the wing, so that the maximum balancing forces may be developed thereby acting about the balance axis 2 in a direction to aid upward deflection of aileron A.

An up-only aileron A of the embodiment hereof is mounted and supported on the hinge arms 4 and 4' which arms at their forward ends are pivotally mounted for rotation or vertical swinging about the remote hinge axes 3, respectively, by means of horizontally disposed hinge pins and suitable anti-friction bearing assemblies 3a attached to and supported on suitable fixed structure of the wing W at a relatively slight 45 distance below the upper surface or skin of the wing, and spaced forwardly a distance from the aileron A, as will be clear by reference to Figs. 3 and 4 of the drawings. The hinge arms 4 and 4' are disposed chordwise of the wing, spaced 50 suitable distances apart along the span of the aileron and extending rearwardly from the pivotal mountings 3a, respectively, to the aileron A and terminating at their rear ends, spaced a slight distance forwardly of the aileron spar or beam 1. The upper surface of the wing W is 55 slotted or cut away to receive the hinge arms and to permit of vertically swinging the arms, while the aileron is vertically slotted or cut away to receive the rear end portions of the hinge arms, and to permit of the vertical rotation of the aileron on and relative to such arms without interference therefrom. Any desired number of hinge arms 4 and 4' may be provided along the span of an aileron A, the number usually being 60 dependent upon the length of span of any particular aileron installation. The aileron hinge arms 4 and 4' are preferably formed of U or channel shape in cross section, with the closed side of the section forming the upper side of the arm, as shown by Fig. 7. Arms 4 and 4' gen-

erally differ only in their respective widths, the arm or arms 4 of an installation being of greater width for the purpose of operative connection and association of the aileron actuating mechanism thereto and therewith, while an arm 4' is of lesser width, in that such arm need only be associated with and carry a portion of an aileron trimming tab adjusting mechanism to be referred to and described hereinafter.

An aileron A is mounted in position on and extending across the rear ends of the spaced hinge arms 4 and 4' for vertical rotation on such arms about the aileron balance axis 2. As an instance of the form which such pivotal mounting of an aileron A on the hinge arms may take, reference is made particularly to Fig. 3 of the drawings, in which a forwardly extended bracket member 2a is shown fixed to the spar or beam 1 of the aileron. Such bracket 2a includes the vertically disposed, horizontally spaced and forwardly extended arms 2b having the horizontal hinge pin 5 mounted thereon between the forward ends thereof in any suitable or desired anti-friction bearings. Brackets 2a, carrying the hinge pins 5, are fixed to the aileron spar 1 at spaced intervals therealong, corresponding to and aligned with the hinge arms 4 and 4', respectively, and the rear ends of these bars are mounted on and connected to the hinge pins 5 with such pins forming and defining the balance axis 2 on and about which the aileron A is rotated in carrying out the vertical deflection of the aileron in accordance with the invention.

Thus, with the aileron A mounted and supported on the hinge arms 4 and 4' for rotation thereon about the balance axis 2 by upwardly swinging the hinge arms 4 and 4' about the remote hinge axis 3, the aileron A can be bodily raised from its normal neutral position forming a portion of the upper surface of the normal contour of the wing W to a position raised above the wing, fully exposed to the air flow rearwardly over the wing upper surface. Such bodily raised position of aileron A is shown by full lines in Fig. 3, and it will be apparent that when the aileron is in such raised position the balance B is fully exposed to the air flow for the reaction of the latter thereon throughout vertical rotation of the aileron about the balance axis to upwardly deflect the aileron to control positions. The air flow rearwardly over the wing will react upon the upper or forward surface of the balance B to force such balance B downwardly, and thus develop forces acting about the balance axis in a direction to aid in the upward deflection of the aileron A. It will be apparent that as the upward deflection of the aileron progresses, with corresponding downward and rearward deflection of the balance B, there will result a progressive increase in the balance forces developed.

The vertical rotation of the aileron A about its balance axis 2 for upward deflection, may be carried out, either during the raising of the aileron bodily by the hinge arms, or throughout a portion of the raising movement of the aileron, or after the aileron has been moved to its maximum bodily-raised position; but in any event, it is desirable that movement of the aileron from its normal neutral position to its maximum upwardly-deflected, or any intermediate, control position about the balance axis 2, should be possible as a continuous, uninterrupted and progressive movement, without time lapse in changing the movement of the aileron from a movement about the remote hinge axis 3 to a movement

about the balance axis 2. Similarly, the lowering of the aileron from any upwardly-deflected control position about the balance axis 2, followed by bodily lowering of the aileron about the remote hinge axis in order to return the aileron to normal neutral position, should be capable of being carried out as a continuous, uninterrupted and progressive movement.

For the purpose of actuating an up-only aileron A in accordance with the invention, I have provided an arrangement of mechanism for bodily raising and lowering such an aileron about its remote hinge axis, and for vertically rotating the aileron about its balance axis, to and from control positions. This mechanism, in the particular example hereof, includes a toggle linkage for bodily raising and lowering the aileron about the remote hinge axis 3 and an associated parallel linkage for vertically rotating the aileron about the balance axis 2. Referring now to Fig. 3 of the drawings, the toggle linkage includes a bell crank 10, mounted for vertical rocking about a horizontally-disposed bearing pin 11, which pin is mounted on and supported between the spaced, rearwardly-extending plates or arms of a bracket 7, that is fixed to and extends rearwardly and upwardly from the rear wing spar 6 of wing W.

The bell crank supporting bracket 7, formed by the spaced arms 1a and 1b, is, in this instance, disposed in a vertical position beneath an aileron hinge arm 4, with the upper end of the bracket spaced a distance below the wing upper surface. (See Fig. 3.) The bracket 7 is offset laterally relative to the longitudinal axis of the arm 4, to a position in proximity to the adjacent side wall of the arm but spaced a sufficient distance therefrom to provide operating clearance for the end or head of the bearing pin or bolt 11 for the bell crank 10, as clearly shown by Fig. 6 of the drawings. In its lowered, neutral position the hinge arm 4 receives the bell crank arm 10a, the bearing bolt 11 and the upper ends of arms 7a and 7b of bracket 7, between its side walls, with the upper or top side wall of arm 4 having clearance space with such elements of the bracket and bell crank assembly. The upper and rearwardly-disposed arm 10a of bell crank 10, is disposed and terminates with its rear end spaced a distance below the leading edge portion of aileron A and balance B when the latter is in normal, lowered, neutral position, and this end of bell crank arm 10a is pivotally connected to the hinge arm 4 thereabove by a link 12. The lower end of link 12 is coupled to the end of arm 10a by a bearing pin or bolt 14 while the upper end of this link is pivotally connected to the hinge arm 4 by a bearing bolt or pin 15, which pin may be mounted extending between and supported by the opposite side walls of the channel section hinge arm 4. Suitable washers, sleeves or other spacing members 15a (see Fig. 6) may be employed to properly position the upper end of link 12 on pin 15 relative to the hinge arm side walls. Thus, with the toggle linkage formed by bell crank 10 and link 12, vertical rocking of the bell crank 10 will, through the medium of the link 12, raise and lower hinge arm 4 to thereby raise and lower aileron A, supported on said hinge arm, to and from its position raised bodily above the wing.

An actuating rod 16 of the push-pull type is pivotally coupled at its rearward end, to the lower or free end of the depending arm 10b of bell crank 10 and this rod 16 extends forwardly into the wing, through rear spar 6, the latter

being suitably cut away to receive the rod and permit operating movements thereof without interference. Horizontally disposed within the wing, a distance forward of rear spar 6, and in this instance forward of the vertical plane passing through the remote hinge axis 3, a bell crank 17 is mounted in horizontally disposed position for swinging about a vertical axis provided by a suitable bearing pin 17a. The bell crank 17 is supported by any suitable bracket or other supporting structure (not shown) in the desired position and location within the wing W. The bell crank 17, referring to Fig. 2a of the drawings, in connection with Fig. 3, includes a cross arm 17b in neutral position generally disposed chordwise of the wing, with the crank arm 17c extending generally rearwardly and outwardly therefrom relative to the wing, at an acute angle to the cross arm, for rotation about the axis provided by bearing pin 17a. The rear end of this arm 17c is pivotally coupled to the forward end of the actuating rod 16 by means of a vertically disposed bearing pin 17d mounted in arm 17c, with a suitable anti-friction bearing of the self-aligning type mounting the end of rod 16 on such bearing pin. Rocking or swinging bell crank 17 about bearing pin 17a in a clockwise direction, referring now to Fig. 2a, forces rod 16 rearwardly to thereby rock bell crank 10 to swing arm 10a thereof upwardly and through link 12, to raise hinge arm 4 and thereby swing such arm about the remote hinge axis 3 to bodily raise aileron A from its neutral position to a position spaced above the wing and exposed to the air flow, for rotation of the aileron about its balance axis 2 for vertical angular deflection thereof relative to the wing for control. The reverse movement of the toggle linkage to lower aileron A to neutral position is accomplished by rotating crank 17 in an anti-clockwise direction to swing arm 17c thereof to draw rod 16 forwardly and thus rock crank 10 to lower hinge arm 4 and the aileron A, supported thereon to neutral position of the latter.

The arrangement of the toggle linkage, referring now to Fig. 3, is such that as crank 10 is rocked to swing arm 10a thereof upwardly and raise aileron A, the crank arm 10a and the connecting link 12 move toward straight-angle relationship. In the maximum raised position of the aileron A, the foregoing arm 10a and a link 12 forming the toggle linkage, very nearly approach straight-angle relationship so that but a minimum of the control forces transmitted to the actuating mechanism by upward deflection of the aileron A about its balance axis, into the air flow, will be transmitted through crank 10 and its actuating mechanism to the control system. The arrangement of the toggle mechanism is such, however, that even in raised position of the aileron A about the remote hinge axis 3, straight-angle relationship is never attained between crank arm 10a and link 12, so that this aileron raising and lowering mechanism remains reversible throughout its full range of operation.

An aileron A of the up-only aileron system of this invention is disclosed in dotted outline in its lowered normal neutral position in Fig. 3 of the drawings, and the bell crank 10 and link 12 of the toggle linkage are shown by dotted lines in their positions for this neutral position of aileron A. Aileron A of Fig. 3, with the toggle linkage and associated actuating means, is shown in full lines in position with the aileron partially raised but approaching its maximum raised posi-

tion. In the arrangement of the present example the hinge arm 4 of an aileron A is raised or swung upwardly about the remote hinge axis 3 through approximately 11° in order to raise the aileron A a sufficient distance above the wing to permit of upward deflection of the aileron about the hinge axis 2 without blanketing balance B and in order to give ample operating clearance between the wing structure and the leading edge of balance B, in the maximum upwardly-deflected position of aileron A.

However, the range of upward swing of the aileron hinge arms and the distance to which the aileron A is bodily raised above the wing on such arms, is a matter of choice dependent upon the design and construction factors of each installation and the invention is in no sense limited or restricted to the foregoing angular range of upward swing of aileron A about the remote hinge axis 3, of the present example. As the primary purpose of bodily raising the aileron above the wing is to render the balance B thereof fully effective, it may, therefore, be said that it is preferable to limit the range of upward swing to that range necessary to attain this end, in the average installation. Further, while the aileron, when so bodily raised about the remote hinge axis, is angularly displaced relative to the wing, therefore, has started to function as a lateral or roll control surface; yet, the angular deflection is of necessity relatively small and the rolling moment developed thereby cannot be large. This fact is, however, taken advantage of in that the control forces, or hinge moments developed during the bodily raising of the aileron A about the remote hinge axis 3 and prior to the effective operation of the balance B by upward deflection of the aileron about the balance axis 2, will be of such small magnitude as to not interfere with the said operation of the control system through this initial range of aileron angular deflection, prior to upward deflection of the aileron about the balance axis 2.

The actuating mechanism for an up-only aileron A also includes a parallel linkage arrangement for rotating the aileron A about the balance axis 2 in vertically deflecting the aileron to and from control positions. This parallel linkage is associated with the hereinbefore described toggle linkage for bodily raising and lowering the aileron to and from its neutral control position. This association is preferably such a one as in the examples hereof in which provision is made for initiation of the rotation of the aileron to upwardly deflect the same about the balance axis prior to the bodily raising of the aileron about the remote hinge axis to its maximum raised position, so that upward deflection about the balance axis takes place simultaneously with and during the upward movement of the aileron about the remote hinge axis.

The arrangement and operative coupling and association of the parallel linkage with an aileron A and the toggle linkage therefor is shown, particularly, in Fig. 3 of the drawings, and includes a crank 18 fixed to the aileron wing spar 1, and extending forwardly and downwardly therefrom. A bolt 18a is secured extending transversely through the free end of crank arm 18 and a distance outwardly beyond opposite sides thereof, to provide opposite bearing pins at the free end of the crank. This crank arm 18 is fixed to aileron spar 1 between the spaced arms of bracket 2a to which the rear end of a hinge arm 4 is pivotally connected, in proximity to the side wall of the

arm 4 opposite the side wall thereof adjacent the bell crank 10. A bell crank 19 is pivotally mounted on and depending from the bearing pin 3a upon which the forward end of a remote hinge bar 4 is pivotally mounted, which pin forms the remote hinge axis 3 about which the aileron is bodily raised. This bell crank 19 is formed with a depending crank arm 19a and with a depending crank arm 19b of greater length than the arm 19a, so that, the end of arm 19b terminates a distance below the end of arm 19a with these two arms in relatively slight angular relationship circumferentially about the remote hinge axis 3. The crank arm 19a is operatively coupled and connected with the crank 18 of aileron A by a rod 20, this rod 20 being pivotally connected at its forward end to the crank arm 19a by a horizontally-disposed bearing pin 20a and being pivotally coupled at its rear end to the bearing pin 18a at the forward end of the bracket 18. The distance between the remote hinge axis 3 about which crank arm 19a rocks and the bearing pin 20a at the lower end thereof to which the forward end of rod 20 is connected, is the same as and equivalent to the distance between the balance axis 2 of the aileron A and the axis of the bearing pin 18a of the crank 18 to which the rear end of rod 20 is connected. Thus, a parallel linkage is formed by hinge arm 4 and actuating rod or link 20 with the cranks 18 and 19a pivotally connecting the adjacent opposite ends, respectively, of arm 4 and rod 20, so that, rocking of the crank 19 about the remote hinge axis 3 will, through the medium of the link or rod 20, rock crank 18 to thereby rotate the aileron A about its balance axis 2.

The parallel linkage for each aileron A is operated to vertically deflect the aileron about its balance axis by an actuating rod 21 pivotally coupled and connected to the depending arm 19b of bell crank 19 by a suitable bearing pin 21a. Actuating rod 21 extends forwardly through the wing W to a bell crank 22 that is mounted in horizontally-disposed position for swinging about a vertical axis provided by a bearing pin 22a. This bell crank 22 includes a main cross arm 22b disposed generally chordwise of the wing, together with the crank arm 22c extended therefrom generally forwardly and inwardly of the wing, and the forward end of actuating rod 21 is pivotally connected to the end of crank arm 22c by a vertically-disposed bearing pin 22d, so that anticlockwise rotation of the bell crank forces actuating rod 21 rearwardly to rock bell crank 19 and thus operate the parallel linkage through rod 20 to upwardly deflect aileron A about its balance axis 2.

It is to be here noted that by utilizing a channel or U-section hinge arm 4, and providing such hinge arm of a sufficient width and by utilizing a bell crank 10 of a material of relatively thin section, the operative association and relative assembly of the toggle linkage and the parallel linkage with this arm, may be carried out in such a way as to permit a compact assembly while attaining operating clearance for the various elements of these linkages and the hinge arm. The rear wing spar 6 is, of course, suitably slotted or cut away from the upper edge thereof downwardly a distance, to give operating clearance for the hinge arm 4 and for the rod 20 of the parallel linkage. With the aileron A in its lowered, neutral position, the hinge arm 4 is disposed substantially within the contour of the normal wing section, and the channel section hinge arm is positioned

over and receives the bell crank 10, with the rod 20 of the parallel linkages moved downwardly past and clearing the crank 10 and its bearing pin or bolt 11.

5 The opposite ailerons A, each with its actuating mechanism consisting of the associated toggle and parallel linkages, are operated, in accordance with the invention, by a pilot-actuated control mechanism, operatively coupled with the aileron actuating mechanisms to form, with such mechanisms and the opposite ailerons A, a lateral or roll control system embodying the principles of the invention. As an example of control mechanism for alternately actuating the mechanisms for vertical deflecting the opposite up-only ailerons of the system, reference is now made to Figs. 1, 2 and 2a of the drawings. Any usual or other desired pilot's control member or element, such as a control wheel C more or less diagrammatically shown in Fig. 1, is provided at any suitable location or control point in the body or fuselage F and control cables 23 are connected therewith for actuation thereby. These control cables 23 are carried from the control wheel C in any suitable or usual manner, and extend in this instance, in horizontally-disposed parallel relation rearwardly to a bell crank 24 that is located in a central position within the fuselage F intermediate the inner or root ends of the opposite wings W, or within the center section for the opposite wings W, in accordance with the particular conditions of the design of airplane in which the system is installed. The bell crank 24 is mounted in horizontally-disposed position for rocking or swinging about a vertical axis provided by the bearing pin 24a with the main cross arm of this bell crank disposed generally transversely of the fuselage F, and having the cables 23 from control wheel C connected to its opposite ends, respectively.

40 Bell crank 24 is provided with the rearwardly-extended crank arms 24b and 24c which arms are radially disposed from the bearing pin 24a for rotation thereabout as an axis, and diverge outwardly and rearwardly from such axis in angular relationship with their rearward ends spaced apart horizontally. The bell crank 24 in the arrangement of the particular example hereof, is mounted to swing in either direction from neutral about the bearing pin 24a so that by movement of the control member such as the wheel C, the cables 23 are operated to rotate bell crank 24 either in a direction clockwise or anticlockwise about the bearing pin 24a in accordance with the direction of rotation of control wheel C, to thereby swing crank arms 24b and 24c to the left or to the right, respectively.

45 The hereinbefore described aileron actuating mechanism provided for each opposite wing aileron A is operated from the bell crank 24 through an arrangement of reciprocal mechanism that includes a parallel linkage embodying a lever bar 25 mounted in horizontally-disposed position for rotation about a vertically-disposed bearing pin 26, with this lever arm extending rearwardly from the bearing pin in a direction generally chordwise relative to a wing when the control system is in its neutral position. A bell crank 27 is mounted on the bearing pin 26 for rotation thereon in a horizontal plane and includes main cross arm 28 with a crank arm 29 extended inwardly therefrom radially of the axis formed by the bearing pin 26. The rear, free end of the lever arm 25 has a bell crank 30 pivotally mounted for rotation thereon about a ver-

tical axis provided by a bearing pin 31 carried by the lever arm 25, so that this crank 30 has rocking movement about pin 31 independently of lever arm 25, but is bodily moved with and carried by arm 25 when the latter swings about its bearing pin 26. The bell crank 30 includes an inwardly-extended crank arm 32 and an outwardly and rearwardly-extended crank arm 33. Crank arm 32 is connected by a rod or link 34 with the inner free end of crank arm 29 of bell crank 27, this rod or link 34 being pivotally coupled to crank arm 32 by bearing pin 35 and to crank arm 29 by bearing pin 36. The distance between the bearing pins 31 and 35 of crank arm 32 is the same as and equal to the distance between the bearing pins 26 and 36 for crank arm 29, and the distance between the bearing pins 35 and 36 for rod 34 is the same as the distance between the bearing pins 26 and 34 for the cranks 27 and 30 of lever arm 25. Hence, 20 rod or link 34 and lever arm 25 are maintained in parallelism, and crank arms 29 and 32 are maintained in parallelism with the result that these connected elements form a parallel linkage for transmitting movement of the bell crank 24 upon actuation thereof by the control wheel C, to the aileron actuating mechanism. Movement of the ball crank 24 is transmitted to the parallel linkage by the actuating rod or link 37 that is pivotally connected at one end thereof to the 30 rear, free end of crank arm 24b by a bearing pin 38 and pivotally connected at the opposite end thereof to the outer free end of arm 33 of crank 30 of the parallel linkage by the bearing pin 39 mounted on and carried by said crank 35 arm 33.

A stop member 40 is mounted on and preferably adjustably secured to, any suitable or desired fixed supporting structure (not shown), with this member 40 positioned adjacent the rear end of lever arm 25 at the inner side of such arm so as to be engaged by the arm to maintain the same in a pre-determined position against inward swinging from such position. A compression spring or other force-exerting unit 41 is pivotally connected to the lever arm 25 at the outer side thereof at 42, substantially opposite the stop member 40 in this instance, and this spring or force unit extends outwardly therefrom and is secured at its outer end at 43 to a suitable fixed structure (not shown). The spring unit 41 is arranged and mounted to continuously exert a force acting on the lever arm 25 to swing this arm inwardly and normally maintain the same against the stop member 40 and thereby normally restrain the arm from outward swinging about its bearing pin 26. In order to swing arm 25 from its position against stop member 40 it is necessary to apply thereto a force of sufficient magnitude to overcome the force exerted by the spring unit 41 and after arm 25 has been swung outwardly by such a force against spring unit 41, upon release of the outward swinging force, the force of spring 41 will act to return arm 25 to its position against stop 40.

The arrangement of the above parallel linkage of the reciprocal mechanism of the system is such that rotation of bell crank 24 in a clockwise direction about its axis 24a will swing the crank arm 24b to the left and through the rod 37, crank 30 will be rocked to swing arm 32 thereof forwardly. During this operation, the lever arm 25 on which crank 30 is mounted and carried, will be forced and held against stop member 40 by the forces exerted by the spring 75

unit 41 and by the forces applied to crank 30 by rod 37, such forces acting on the rear, free end of arm 25 in a direction tending to swing this arm inwardly of the wing W about the bearing pin 26 at the forward end of the arm. Forward swinging of crank arm 32 forces the rod 34 of the parallel linkage mechanism forwardly and crank arm 29 of the bell crank 27 is thus swung forwardly to rock or rotate bell crank 27 in a clockwise direction about the bearing pin 26 on which this crank is mounted at the forward end of lever arm 25.

Clockwise rocking of crank 27 is transmitted through cables 44 and 45 to a bell crank 46, referring now to Fig. 2a, that is located spaced a distance outwardly in the right wing W. Bell crank 46 embodies a cross arm 48 and a cross arm 49 with the bell crank mounted in horizontally-disposed position for rotation or rocking about a vertically-disposed bearing pin 47. Cables 44 and 45 are connected between the forward and rear ends, respectively, of the cross arm 48 and the forward and rear ends of the cross arm 28 of the bell crank 27, so that rocking of bell crank 27 correspondingly rocks bell crank 46 about its bearing pin 47. The cross arm 49 of bell crank unit 46 is disposed in angular relation to cross arm 48 and provides the generally forwardly and inwardly disposed crank arm 50 for actuating the toggle linkage of the actuating mechanism for aileron A of this right wing W, and provides the oppositely extending generally outwardly and rearwardly disposed crank arm 51 for operating the parallel linkage of such aileron actuating mechanism.

Adjacent, but disposed outwardly of the right wing W, from the bell crank unit 46, a bell crank 52 is mounted in horizontally-disposed position for rocking about the vertical bearing pin 53, with this bell crank embodying a main cross arm 54. Bell crank 52 includes a crank arm 55 angularly disposed relative to main cross arm 54 and extending radially from bearing pin 53 in a general forward and inward direction relative to the wing. A link or connecting rod 56 extends between and pivotally connects the end of crank arm 55 of bell crank 52 with the end of the crank arm 51 of bell crank 46. The crank arms 51 and 52 extend generally in opposite directions from their respective pivot points, so that the direction of rotation imparted to the bell crank 52 by rotation or rocking of bell crank 46 is always opposite the direction of rotation of the latter. The connecting rod or link 56 is pivotally coupled at its inner end to the outer end of crank arm 51 by a bearing pin 57 and is coupled at its opposite outer end to the end of crank arm 55 by a bearing pin 58, suitable anti-friction bearings being carried by the opposite ends of link 56 for mounting upon these bearing pins, respectively. The bell crank 52 is operatively coupled with the bell crank 22 from which the parallel linkage of the aileron actuating mechanism is operated. The bell crank 22 is spaced a distance outwardly in the right wing W from bell crank 52, with these bell cranks aligned spanwise of the wing, and the respective cross arms 54 and 48 thereof of the same length. The operative connection of bell crank 52 with bell crank 22 is carried out in this instance, through the medium of the cables 59 and 60 that are pivotally connected between the opposite ends, respectively, of the cross arm 54 of crank 52 and the cross arm 22b of bell crank 22.

The bell crank 17 for operating the toggle

linkage of the aileron actuating mechanism, is also operated by and from the bell crank 46. In this particular example, the bell crank 17 is mounted in the wing W spaced a distance rearwardly from bell crank 22 and offset inwardly a slight distance therefrom, and this bell crank 17 is operatively coupled with the bell crank 61 that is spaced a distance inwardly of the wing from bell crank 17 but aligned spanwise of the wing therewith. The bell crank 61 is disposed within the wing to the rear of, but intermediate the bell cranks 46 and 52, and includes a cross arm 62 that is connected at its opposite ends with the opposite ends, respectively, of the cross arms 17b of bell crank 17 by the cables 63 and 64. The bell crank 61 is mounted in horizontally-disposed position for rocking about a vertical pivot or bearing pin 65 and is provided with a crank arm 66 that extends radially from bearing pin 65 at a slight angle relative to cross arm 62 and in a rearward direction relative to the wing. Bell crank 61 is operatively coupled with the bell crank 46 through the medium of a connecting rod or link 67. This connecting rod or link 67 is pivotally connected at its forward end with crank arm 50 of bell crank 46 by means of an offset bearing pin 68 and is operatively coupled at its opposite end with the rear end of crank arm 66 by an offset bearing pin 69, the arrangement being such that connecting rod or link 67 is disposed at and spaced inwardly of the wing from the ends of the crank arms 50 and 66. Preferably the ends of rod 67 are provided with suitable anti-friction bearings by which they are mounted on the bearing pins 68 and 69, respectively. By this arrangement, clockwise rocking of the bell crank 46 about the bearing pin 47 swings crank arm 50 forwardly and through the connecting rod or link 67, rocks crank arm 66 of bell crank 61 inwardly and forwardly to rotate the bell crank 61 in a clockwise direction. Clockwise rotation of bell crank 61 rotates bell crank 17 through cables 63 and 64 in a clockwise direction to thereby swing crank arm 17c in a clockwise direction to force actuating rod 16 rearwardly to actuate the toggle linkage to raise the aileron A of this right wing W, in the manner as hereinbefore described.

In the control operation of the disclosed system, referring now particularly to Figs. 1 and 2 of the drawings in which the right wing aileron is disclosed, if the pilot desires to raise this right aileron, in order to lower the right wing, the control element or wheel C is operated in a clockwise direction to swing bell crank 24 in a clockwise direction about its bearing pin 24a. Clockwise rotation of bell crank 24 swings or rotates crank arm 24b to the left, referring now to Figs. 2 and 2a of the drawings, and through rod 37 rocks crank 30 in a clockwise direction, with the forces reacting on arm 25 in a direction to maintain this arm in position engaging the stop member 40 and held thereby against inward swinging or displacement, this arm 25 also being subjected to the forces exerted by spring 41, acting thereon to maintain the arm against the stop member 40.

Bell crank 24 is designed and mounted for rocking through 50° in either direction about its bearing pin 24a in this specific instance, and the design and arrangement of the parallel linkage through which the right aileron A is actuated to control positions is such that a 10° movement of bell crank 24 will result in a 20° move-

ment of the crank arms 32 and 29 of the parallel linkage. Thus, with the operation of the system to raise the right aileron A for control, upon rocking bell crank 24 in a clockwise direction through the first 10° of its movement, the right wing parallel linkage has the crank 30 rocked in a clockwise direction about its bearing pin 31 through 20° to thereby actuate the parallel linkage to rock crank arm 29 and the bell crank 27 in a clockwise direction through 20° of their range of movement. The bell crank 24 and associated mechanisms for the right wing aileron A are shown in full lines in their respective positions with crank 24 swung through the first 10° of its range of movement in a clockwise direction.

The rocking of the bell crank 27 through the first 20° by the actuation of the parallel linkage results in rocking the bell crank 46 through the medium of the connecting cables 44 and 45, through 20° in a clockwise direction. This clockwise swinging of bell crank 46 also swings crank arm 50 thereof through 20° of its movement and thereby moves the connecting link or rod 67 forwardly to rock bell crank 61 in a clockwise direction about its axis formed by the bearing pin 65. The relative arrangement of the crank arm 50 of bell crank 46 and the crank arm 66 of bell crank 61 with the connecting rod or link 67 coupled by the offset pivot points between these crank arms is such that this 20° movement of bell crank 46 is translated into substantially a 42° movement of bell crank 61, to the full line position thereof shown in Fig. 2a, in the specific example hereof. The swinging of bell crank 61 in a clockwise direction in turn swings bell crank 17, through the connecting cables 63 and 64, in a clockwise direction, through substantially a 42° range of movement about its axis or bearing pin 17a, to the full line position thereof as shown in the drawings.

The crank arm 17c of bell crank 17 is thus rotated or swung inwardly and rearwardly through approximately 42° and forces the actuating rod 16 rearwardly to thereby rock the crank 10 of the toggle linkage for the right aileron A, upwardly. Upward swinging or rocking of crank 10 about its bearing pin 11 swings the aileron hinge arm 4 to which it is connected by link 12, upwardly about the remote hinge axis 3 to thereby bodily raise this right wing aileron A from its normal neutral position (shown by dotted lines in Fig. 3), to control position raised above the wing and disposed in the air flow over the upper surface of the wing. This raised position of aileron A, resulting from operation of the pilot's control wheel C to swing the bell crank 24 through approximately its first 10° of movement is shown by full lines in Figs. 3 and 4 of the drawings. In this raised position that corresponds to the approximately initial 10° movement of bell crank 24, the aileron A is not as yet in its maximum bodily-raised position, but very nearly approaches this position so that there remains but a relatively small degree of movement necessary to swing aileron A to its maximum raised position. With the aileron A in its bodily-raised position, resulting from the initial 10° movement of the bell crank 24, and closely approaching its maximum raised position, it is to be noted that the arm 10a of crank 10 of the toggle linkage approaches straight-line relationship with the link 12 of this linkage, and while the control forces that will be developed in raising and holding aileron A in its bodily-raised position, will be of relatively small

magnitude, yet, due to the near straight-angle relationship of the foregoing arms 10a and 12 of the toggle linkage, the major portion of such control forces will not be transmitted through the system to the pilot's control operating member, such as the wheel C of this example.

During the foregoing actuation of the toggle linkage to bodily raise aileron A about its remote hinge axis 3, the swinging of bell crank 46 in a clockwise direction through approximately 20°, swings crank arm 51 rearwardly and through connecting rod or link 56 results in rocking the bell crank 52 in an anti-clockwise direction about its axis 53 to swing the cross arm 54 of this bell crank through only approximately 10° in an anti-clockwise direction to the full-line position thereof shown in Fig. 2a. This 10° of movement of cross arm 54 of bell crank 52 is transmitted through cables 59 and 60 to the cross arm 22b of crank 22, so that this crank is swung in an anti-clockwise direction through approximately 10° of movement. Such rocking of crank 22 swings the crank arm 22c thereof inwardly and rearwardly of the wing to thereby force actuating rod 21 for the parallel linkage of the aileron actuating mechanism rearwardly to rock crank arm 19b of the bell crank 19 that is mounted for rocking about the remote hinge axis 3 rearwardly through approximately 5° of movement to the full-line position of this bell crank 19 shown in Fig. 3. The rearward rocking or swinging of crank arm 19b rocks crank arm 19a rearwardly to actuate the parallel linkage through rod or link 20 and crank arm 18 to rotate aileron A about its balance axis 2 to an upwardly-deflected position, displaced through an angle of approximately 5°, as shown by the full-line position of aileron A in Figs. 3 and 4. Thus, in the bodily raised full-line position of aileron A, shown in Fig. 3 of the drawings, the parallel linkage of the aileron actuating mechanism has been simultaneously operated with the bodily raising of the aileron by the toggle linkage so that the aileron has not only been bodily raised, but has also been upwardly deflected through an angle of approximately 5°. In order to swing the aileron A to its maximum upwardly-deflected position, shown by dotted lines in Figs. 3 and 4, such maximum position being an angular displacement through approximately 40° of the control wheel C is further operated to rock bell crank 24 through the remaining 40° of its range of movement in a clockwise direction. Such further swinging of bell crank 24 rocks bell crank 46 and the crank arms 50 and 51 thereof, in a clockwise direction through the remaining 40° of the total range of swing of 60° of said bell crank. The swinging of crank arm 51 in a clockwise direction swings bell crank 52 further in an anti-clockwise direction, through the remaining approximately 40° of its 50° of total movement, by means of the connecting rod 56. Rocking of bell crank 52 then actuates the parallel linkage by means of the bell crank 22, to further upwardly deflect the aileron A through the remaining approximately 35° of its upward deflection to its maximum control position shown by the dotted line position of aileron A in Figs. 3 and 4.

While the upward deflection of aileron A to its maximum control position is being carried out, the rocking of crank arm 50 of bell crank 46 causes connecting rod or link 67 to further rock bell crank 61 in a clockwise direction, but, due to the relationship between the crank arm 50 of bell crank 46 and the crank arm 66 of bell crank

61 and of the connecting rod or link 67, the cross arm 62 of bell crank 61 is further rocked in a clockwise direction through only approximately 18° of movement. Cross arm 17b of bell crank 17, together with crank arm 17c, is thus rocked through cables 63 and 64 by this 18° of movement of bell crank 61 and through 18°, but with crank arm 17c and the actuating rod 16 for the toggle linkage approaching straight-angle relationship, as will be clear from the full-line position of these elements in Fig. 2a, the further rearward movement of rod 16 resulting from the 18° movement of crank arm 17c is materially reduced, and results in rocking the bell crank 10 through the remaining relatively small degree of its total range of movement necessary to complete the bodily upward swinging of aileron A into its maximum raised position. This final movement of crank 10a and the connecting link 12 will be relatively slow in relation to the rate of upward deflection of the aileron A about its balance axis 2 through the remaining 35° of the aileron deflection, and the hinge arm 4 and the aileron A will not reach their maximum bodily-raised positions swung upwardly about remote hinge axis 3, until aileron A has been rotated about balance axis 2 to reach its maximum angle of 40° of upward deflection relative to wing W. Even in the maximum raised position of aileron A, crank arm 10a and link 12 will not attain straight-angle relationship and the toggle linkage, therefore, remains reversible.

The aileron A is raised by the toggle linkage to a position fully exposing the balance B of the aileron to the air flow rearwardly over the wing, and, therefore, upon rotation of the aileron A about its balance axis 2 by the parallel linkage of the aileron actuating mechanism, the maximum balancing forces possible from balance B are developed acting about the axis 2 in a direction to materially aid the upward deflection of the aileron to control positions and thereby substantially reduce the control forces applied to the control system, and that must be overcome by the pilot in operating the control system. Due to the design, arrangement and mounting of the mechanisms embodying the control system as hereinbefore described, it is apparent that the aileron A can be actuated from its normal neutral and at rest position to its maximum upwardly-deflected control position with the aileron swung or rotated about the separate widely spaced hinge axis 3 and balance axis 2 by a continuous, smooth and uninterrupted movement of the pilot's control member, such as the wheel C of the present example. The mechanisms are such that in this instance, in a control operation of the aileron, rotation thereof about the separate hinge and balance axes takes place substantially simultaneously, but at different relative rates of movement, during portions of the operating range. However, my invention is in no sense limited or restricted to such operation as, if desired and found expedient, rotation of the aileron about its balance axis may be initiated after the aileron A has been raised to substantially maximum position, or upon the aileron A reaching any raised position between neutral lowered position and its maximum raised position. The angle through which the aileron A is bodily raised from neutral position about remote hinge axis 3 in order to fully expose aileron balance B to the airflow, is sufficiently small to require but relatively small movement of the pilot's control member C to accomplish, and with the simulta-

neous angular deflection of the aileron A relative to the wing W resulting from such movement, there is no material lag between the operation of the control and the rolling response therefrom.

The up-only aileron A of left wing W is actuated by an arrangement of mechanisms in all respects identical to the mechanisms of the control system hereinbefore described in detail in connection with the operation of the aileron A of the right wing W, and it is not deemed necessary to describe this duplicate mechanism in detail. In Fig. 2 of the drawings, that portion of the left wing aileron operating mechanism of the system is disclosed that consists of the left wing parallel linkage that is coupled with the bell crank 24 operated by the pilot's control wheel C through the operating cables 23, and the elements of this parallel linkage and of those portions of the associated mechanism that are disclosed have been given identical reference numerals as those used for such elements of the corresponding mechanisms of the right wing aileron, except that each of these reference numerals has been primed. For example, the crank arm 24c of bell crank 24 is connected with the bell crank 30' of the parallel linkage for the left wing aileron A by the actuating rod 37', which rod is pivotally coupled at its inner end to crank arm 24c by the bearing pin 38' and at its outer end is coupled to the free end of crank arm 33' of bell crank 30' by the bearing pin 39'. The cross arm 28' of the bell crank 27' of the parallel linkage has the cables 44' and 45' connected therewith, which cables correspond to cables 44 and 45 of the mechanism of the right wing aileron, and lead to mechanisms in the left wing W corresponding to those hereinbefore described in connection with right wing aileron A for transmitting aileron actuating movements from bell crank 27' to the left wing aileron A.

The inherent static unbalance of an up-only aileron type of lateral or roll control system is eliminated or substantially reduced in accordance with the principles of my invention, in the particular example hereof, by the application of a force to each of the opposite up-only ailerons A, respectively, of the system, which force continuously acts to bodily raise each aileron upwardly about its remote hinge axis 3 from the normal neutral, at-rest position of the aileron. As an example of one possible method of generating and applying such a force to an up-only aileron, I have provided a spring unit 70, referring now particularly to Figs. 2a and 3 of the drawings, in which such a unit is shown in association with the aileron A of the right wing W of the airplane, the spring unit 70 in this particular example being operatively coupled to the toggle linkage of the aileron actuating mechanism. Such a spring unit 70 may be of the coil, extensible type as here shown, and may be secured at its rear end to suitable fixed structure, such as the wing spar 6, by a pivotal connection 70a and extend forward and be attached to a suitable bracket or fitting 70b fixed on the outer end portion of crank arm 17c by a pivotal connection 70c. Thus, this spring unit 70 is mounted in position connected between the fixed attachment point 70a and the crank arm 17c for actuating the toggle linkage for raising and lowering the aileron A, so that this unit continuously exerts a force on the crank arm 17c acting in a direction to swing this arm clockwise about

its axis 17a to thereby continuously tend to force actuating rod 16 rearwardly to raise aileron A from its normal, at-rest position. A similar force unit 70 is associated with the opposite left wing aileron A and applies forces continuously acting to raise that aileron from its normal, at-rest position, in the same manner as described in connection with the spring unit 70 for the right wing aileron A.

While I have disclosed in this particular example a spring unit as the means for generating and applying the raising force to an aileron A, it is to be understood that my invention is not limited to any particular type of means or mechanism that may be employed for generating and applying the required forces, but the invention contemplates and includes any suitable or desired means or mechanism adapted to or suitable for this purpose. This feature of my invention broadly consists in the elimination or reduction of static unbalance in an up-only aileron type of lateral or roll control system by the application of a force to an up-only aileron that acts independently of and in addition to the force applied to the system to raise an aileron from its normal, at-rest position by pilot operation of the system; such independent force being primarily applied for the purpose of removing from the system the inertia loads that are encountered in picking up and raising an aileron from its neutral, at-rest position when the system is operated by the pilot. Further, it is to be noted that with the specific type of means of the present example, the force is continuously applied to the aileron, but the invention is not so limited, as, if desired, a type or arrangement of force generating means may be utilized that only applies such force when the aileron is being upwardly deflected.

In order to facilitate a clear understanding of the discussion which follows, and referring again to Figs. 2a and 3 of the drawings, I should like to call particular attention to the fact that when the right wing aileron A has been fully retracted from an upwardly raised, control position to its neutral, at-rest position, rod 16 will have been drawn forward to the limit of its reverse-control movement, crank arm 17c of bell crank unit 17 will have been rotated in an anti-clockwise direction to the limit of such anti-clockwise movement, and spring unit 70 will be fully extended and continuously applying a force tending to rotate bell crank unit 17 in a clockwise direction to move rod 16 rearwardly and raise aileron A. Bell crank unit 17 is operatively coupled, through the medium of cables 63 and 64, to a second bell crank unit 61, as hereinbefore described. It must be clear, then, that if right wing aileron A is in its fully retracted or neutral position, and bell crank unit 17 has reached the limit of rotation anti-clockwise, bell crank unit 61 will likewise have reached the limit of its rotation in an anti-clockwise direction. At the same time, the force continuously applied by spring unit 70 tending to rotate bell crank unit 17 in a clockwise direction would apply equally to bell crank unit 61 as a force tending to rotate the latter in a clockwise direction. Similarly with bell crank unit 46, which is operatively coupled to bell crank unit 61 by rod 67; and the same conditions would apply to bell crank unit 27 of Fig. 2, which, through the medium of cables 44 and 45, is coupled into this operating mechanism for actuation of the right wing aileron A.

Thus it will be seen that when right wing aileron A is fully retracted to its neutral, at-rest position, each of several similarly disposed bell crank units in the operating mechanism intermediate the right wing parallel linkage of the reciprocal mechanism and the toggle linkage for the right wing aileron A will reach a limit of rotation in the anti-clockwise direction, coming to rest in a position which may be called its neutral-control position; also, that the force generated by spring unit 70 is continuously applied to each of said bell crank units tending to rotate it in the clockwise and control direction away from its neutral-control position.

Similar conditions, of course, apply to left wing aileron A, except that in this case the direction of rotation of the several bell crank units of the operating mechanism or linkage intermediate the left wing parallel linkage of the reciprocal mechanism and the toggle linkage for left wing aileron A is reversed. In brief, when the left wing aileron A has been fully retracted to its neutral, at-rest position, each of the several bell crank units of the said left wing aileron operating mechanism will have been rotated to the limit of rotation in a clockwise direction, and will be at rest in its neutral-control position; while the force generated by a spring unit 70, operatively associated with the toggle linkage for left wing aileron A, will be continuously applied to each of the bell crank units of the left wing aileron operating mechanism tending to rotate such bell crank unit in the anti-clockwise and control direction away from its neutral-control position.

With the disclosed example of a lateral or roll control system of the up-only aileron type, as described hereinbefore, when the system is in neutral position, the opposite ailerons A are in their lowered, at-rest, neutral positions, forming trailing portions of the upper surfaces of the opposite wings W, as illustrated in the case of the right wing aileron A by the dotted-line position of such aileron in Fig. 3 of the drawings. The control operating mechanisms intermediate the pilot's control wheel C and the opposite ailerons A, referring now particularly to Figs. 2 and 3, are likewise in neutral; with centrally-located bell crank 24 disposed spanwise of the wing; with lever arms 25 and 25' held in the normal, neutral positions thereof, pressed against their respective stops 46 and 46' by the action of spring units 41 and 41' respectively; with bell crank unit 27 at rest in neutral-control position, having been rotated to the limit of movement in an anti-clockwise direction; with bell crank unit 27' in the neutral-control, full-line position of Fig. 2, having been rotated to the limit of movement in the clockwise direction; and with spring units 70, operatively associated with opposite ailerons A, continuously applying forces tending to rotate bell crank 27 in a clockwise direction and bell crank 27' in an anti-clockwise direction.

Starting with such neutral-control position for the system as a whole, if the pilot now moves the control wheel C in a clockwise direction—the natural movement of such a pilot-controlled element to depress the right wing and raise the left wing; and if such clockwise rotation of control wheel C is merely sufficient to rock bell crank 24 in a clockwise direction through the first 10° of its movement from a neutral-control position; then rod 37 will be moved slightly to the left as shown, bell cranks 30 and 27 will be rotated in a clockwise direction to the full-line positions 75

thereof in Fig. 2, and right wing aileron A will be raised from its neutral, at-rest position to the bodily-raised, angularly-deflected, full-line position of Fig. 3, all as hereinbefore described. But 5 insofar as this movement applies strictly to actuation of the right wing aileron mechanism, and particularly during the initial stages of such movement, this clockwise rotation of control wheel C to rock bell cranks 24, 30 and 27 in a 10 clockwise direction requires no effort on the part of the pilot; because spring unit 70, operatively associated with the right wing aileron operating mechanism, is continuously applying forces tending to rock bell cranks 27 and 30 in a clockwise 15 direction, and is thus developing a compression force in rod 37 tending to rock bell crank 24 in a clockwise direction. In effect, then, pilot movement of the control wheel C in a clockwise direction merely serves to release the potential energy 20 of the spring unit 70 operatively coupled with the actuating mechanism for right wing aileron A, and said spring unit 70 is thus enabled substantially to lead pilot actuation of the control system to pick up right wing aileron A from its neutral, at-rest position and start it moving bodily upward about its remote hinge axis 3 to control positions spaced above the upper surface of the wing.

When control wheel C is rotated in a clockwise direction to rock bell crank 24 in a clockwise direction and actuate the right wing aileron A, not only is rod 37 moved to the left, but rod 37', pivotally attached to the outer, free end of crank arm 24c of bell crank 24, is likewise moved to the left. 30 This outward movement to the left on the part of rod 37' might be expected to rock bell crank 30' in a clockwise direction about its bearing pin 31', at least to the limit imposed by the relationship between rod 37' and crank arm 33'. But crank arm 32' of bell crank 30' is a member of the parallel linkage. As such it must constantly maintain a position parallel to crank arm 29' of bell crank 27'. As previously noted, bell crank 27' is at rest in its neutral-control position, having 35 been rotated to the limit of movement in the clockwise direction to fully retract left wing aileron A to its neutral, at-rest position. Since crank arm 29' is unable to move any further in a clockwise direction, crank arm 32' of bell crank 27' cannot be rocked in a clockwise direction, and the force applied to the left wing parallel linkage by outwardly-moving rod 37' serves to hold left wing aileron A securely in its neutral, at-rest position. Continued rotation of bell crank 24 in a 40 clockwise direction to deflect right wing aileron A about its balance axis to high-angle control positions will cause rod 37' to continue moving outward to the left while constantly applying forces to the left wing parallel linkage tending to prevent anti-clockwise rotation of bell crank 27' to actuate the left wing aileron operating mechanism, to raise left wing aileron A from its neutral position to control positions. Thus, it 45 will be seen that with this type of up-only aileron control system, the aileron opposite the upwardly-deflected aileron is maintained in its normal, neutral, at-rest position against displacement during and throughout vertical deflection of the other aileron.

The foregoing discussion implies, in a sense, that the pilot experiences no feeling of control force when moving control wheel C from neutral in the control direction to actuate the right wing aileron operating mechanism to raise the right

wing aileron A from neutral to control positions, due to the force generated and continuously applied to said operating mechanism tending to actuate it in the control direction. True, the pilot has no feeling of picking up the aileron from its at-rest position and setting it in motion upwardly to control positions. He does, however, experience a feeling of control force. This is supplied by the force generated and continuously applied by spring unit 41' of the left wing parallel linkage to resist any movement of lever arm 25' away from its normal, neutral position against stop 40'. Clockwise rotation of bell crank 24 moves rod 37' outwardly to the left, as hereinbefore described. The compression force thus developed in rod 37' is transmitted through the medium of crank arm 33' to the rearward, free end of lever arm 25', and the latter is forced outwardly, compressing spring unit 41' and swinging in a clockwise direction about bearing pin 26' and away from its stop 40'. Spring unit 41' resists such clockwise rotation of bell crank 24 away from its neutral-control position to rock crank arm 24c in a clockwise direction, to move rod 37' to the left, to force lever arm 25' outwardly away from its stop 40'.

Thus, it will be seen that opposing forces are applied to centrally-located bell crank 24 when it is in or near its neutral-control position. Spring unit 70, operatively coupled into the right wing aileron operating mechanism is continuously applying forces tending to rotate bell crank 24 away from its neutral position and in a clockwise direction; while spring unit 41' is continuously applying forces tending to resist rotation of bell crank 24 away from its neutral position in the clockwise direction. The force generated by spring unit 41' and applied thereby to the outer end of relatively long lever arm 25' is designed to slightly overbalance or outweigh the force generated by the spring unit 70 associated with right wing aileron A and made effective through relatively short crank arm 24c. Accordingly it must be clear that if bell crank 24 is to be rocked away from its neutral position in a clockwise direction, some force must be added to that generated by the said right wing aileron spring unit 70. This additional force is supplied by the pilot; and the feeling of control force which he experiences when moving the control wheel C from neutral in the control direction to raise right wing aileron A results from the slight differential between the forces of spring unit 70 and spring unit 41' of the opposite aileron mechanisms. At the beginning of such movement away from neutral, the force needed to be exerted by the pilot is slight—so slight, in fact, that the neutral point in the control system would scarcely be noticed by the pilot if he were swinging control wheel C back and forth through neutral. As this movement continues, however, and bell crank 24 is moved farther and farther in the clockwise direction, the pilot will need to exert an increasing amount of force, due to the increasing magnitude of the force generated by spring unit 41' as it is compressed to a greater and greater extent by the outward swinging of lever arm 25'. In this manner an up-only aileron control system of my invention is given quite a normal, natural "feel" in the hands of a pilot, for the pilot anticipates the feeling of increasing control force when moving a control element such as wheel C outward from neutral-control position toward the full-control position.

Having moved the up-only aileron control system of my invention to the position indicated by the full lines of Figs. 2 and 3 particularly, if the pilot now wishes to reverse the control operation and return right wing aileron A to its neutral, at-rest position, he has merely to reverse the direction of rotation of control wheel C to rock bell crank 24 in an anti-clockwise direction back to its neutral-control position. This action will serve to reverse the movement of parts in the right wing aileron operating mechanism, as hereinbefore described, and right wing aileron A will be retracted to its neutral, at-rest position.

If the pilot continues this anti-clockwise movement of control wheel C on through neutral, in the control direction to actuate the left wing aileron operating mechanism and raise the left wing aileron A from neutral to control positions, bell crank 24 will be rocked through its neutral-control position in the anti-clockwise direction, rod 37 will be moved to the right to force the right wing parallel linkage outwardly to reverse-control positions, and rod 37' will be drawn inwardly to the right, thereby releasing the potential energy of spring unit 70, operatively associated with left wing aileron A, to rotate bell cranks 30' and 27' in an anti-clockwise direction, to actuate the left wing aileron operating mechanism, to raise the left wing aileron A from neutral, at-rest position to control positions, all as hereinbefore described for the opposite wing mechanisms.

An important characteristic of a satisfactory aileron control system is that it should automatically neutralize itself if released by the pilot during control operation. Assuming that the up-only aileron control system of my invention, as herein exemplified, has been moved to the position indicated by the full lines of Figs. 2 and 3, if the pilot now releases control wheel C, it is clear that the aerodynamic force applied to the upwardly-raised and angularly-deflected right wing aileron A will alone be sufficient to partially or nearly return said aileron A to its neutral position. As aileron A moves bodily downward, however, the action of the toggle linkage is reversed, and rod 16 is moved forward to gradually extend spring unit 70 and thereby generate the force designed to raise aileron A from neutral to control positions. In these circumstances, aerodynamic force alone can hardly be expected to fully retract right wing aileron A. It will be recalled, however, that spring unit 41' of the left wing parallel linkage is continuously applying forces tending to return the system to its neutral position; and inasmuch as spring unit 41' represents a force of greater magnitude than that of spring unit 70 operatively associated with right wing aileron A, it must be clear that the system will be neutralized even though the pilot is applying no force in the reverse-control direction. At the same time, it should be noted that spring unit 70, through gradual extension, has served as a damping agent to ease right wing aileron A down into its neutral, at-rest position.

Due to the arrangement of the various mechanisms and their cooperative association, that form and provide the control system, together with the force-applying means for eliminating the inherent static unbalance of the up-only type of aileron, all as hereinbefore described, the pilot can operate the system to raise and lower either aileron A to and from its maximum control position by a continuous and uninterrupted movement of the control system operating member,

such as wheel C. Further, the system can be operated back and forth through neutral to lower one aileron and then raise the opposite aileron, or can be operated to raise one aileron from neutral, without any objectionable "feel" in the control system operating member, because the "dead weight" and inertia loads that would be imposed on the system by picking up and raising an aileron from its at-rest position are eliminated by the raising forces continuously and independently applied to the opposite ailerons. Thus, one of the serious problems and disadvantages of the up-only aileron type of control system is overcome by a system designed to embody the principles and various features of the present invention.

In order to provide for laterally trimming the airplane to correct for a wing heavy condition at one side or the other thereof, the invention provides, as a further feature thereof, the combination with opposite ailerons of the up-only type, of trimming tabs mounted on and operatively associated with such ailerons for independent adjustment, together with suitable pilot operated and independently operable adjusting mechanisms for such tabs. As an example of such trimming tabs, and their adjusting mechanisms, as applied to and combined with the up-only ailerons A of the illustrated form of my up-only aileron control system, I have disclosed, referring now to Figs. 1 and 4 of the drawings, a trim tab T mounted on each aileron forming a trailing portion thereof, along the inboard span of the aileron. Each tab T is identically designed and mounted, and it will suffice to describe the tab T mounted on the right wing aileron A, together with its adjusting mechanism, all as shown particularly in Fig. 4 of the drawings. The tab T is mounted for vertical deflection about a hinge axis disposed spanwise of the leading edge portion of the tab, such hinge axis being formed by a bearing pin 71 that is carried by a suitable bracket or brackets 72. By swinging this tab T downwardly, at an angle relative to the aileron A, the aileron will, of course, be raised as a result of the airflow reaction on the tab, to thus depress or lower the right wing so as to correct for a condition of lateral unbalance that may be caused by left wing heaviness. Similarly, the trim tab T on the left wing aileron A may be lowered or swung downwardly to an adjusted position to raise such aileron in order to depress the left wing to correct for a condition of right wing heaviness. In the particular example hereof, it is to be noted that the depth of a tab T is greater than the depth of the trailing portion of an aileron, A, and that clearance with wing structure below the tab to accommodate such increased depth as well as to permit downward deflection of the tab, is necessary. In this instance, the structure beneath an aileron A and its tab T is formed by a wing flap L, and such flap is cut away or recessed to receive the tab when the aileron A and flap are in their normal neutral positions, as shown by dotted lines in Fig. 4.

The opposite aileron trim tabs T are designed and mounted for independent adjustment and a suitable adjusting mechanism for pilot operation is associated with each up-only aileron A. For example, a depending bracket 73 may be provided suitably fixed or secured to the aileron spar 4, and this bracket pivotally mounts at its lower end a compression link or lever 74 which link extends upwardly from bracket 73 and is adapted

for swinging through a plane chordwise of the wing. A push-pull rod or link 75 is pivotally coupled at its rear end to the trim tab T at a point, in this instance, beneath the hinge axis 5 71 of the tab and extends forwardly and is pivotally coupled to the upper end of link 74 by an offset bearing connection 76. The offset bearing 76 that forms the pivotal connection between push-pull rod 75 and the link 74 is so designed 10 that with the trim tab T in its neutral position, the bearing 76 is in axial alignment with the balance axis 2 of the aileron A. Hence, vertical deflection of aileron A about its balance axis 2 may be carried out without moving the trim tab 15 T from its neutral position, the tab remaining with its position relative to the aileron undisturbed and unchanged throughout aileron vertical deflection.

For the purpose of rocking link 74 in order 20 to angularly deflect the trim tab T relative to aileron A, a pilot operated mechanism is provided that includes a cable drum 77 mounted for rotation in a plane spanwise of wing W about an axis disposed chordwise of the wing. This 25 drum 77 in the present example, is mounted on and carried from the forward end of aileron hinge arm 4' by a bracket 78 that may be riveted or otherwise suitably secured to this hinge arm, and that includes the depending spaced bracket 30 arms 79 between which the cable drum 77 is rotatably mounted. A push pull rod 80 is pivotally connected to the upper end of link 74 on the pivotal bearing 76 and extends forwardly to and axially through the cable drum 77 and the bracket 35 arm 79 of bracket 78. This push pull rod 80 is externally threaded at its forward end at 81 and this threading engages suitable internal threading in an axial bore through drum 77, so that rotation of this drum through the engaged 40 threading will force push-pull rod 80 rearwardly or forwardly in accordance with the direction of rotation of the drum. An operating cable 82 is wound upon the cable drum 77 and extends through the wing to suitable pilot operated mechanism 45 (not shown) for rotating the drum 77 in the desired direction to adjust the trim tab T through the medium of the mechanism hereinbefore described.

In the specific example of a trim tab as shown 50 in Fig. 4 of the drawings, the cable drum 77 has been rotated in the proper direction to draw push-pull rod 80 forwardly and through link 74 and push-pull rod 75 to thereby lower and downwardly deflect tab T. In this instance, the tab 55 has been deflected through an angle of approximately 15° relative to aileron A, the pivotal axis 76 of the adjusting mechanism then being moved from axial alignment with aileron balance axis 2 to a position spaced slightly forward of balance axis 2, as will be clear by reference to Fig. 4. When so adjusted, aileron A may be vertically raised about its remote hinge axis 3 and vertically deflected about its balance axis 2 in the control 60 operation thereof without interference from or by the angularly-deflected trim tab T. The control operation of aileron A will not affect the adjusted position of tab T relative to the aileron except that due to the position of the pivotal bearing 76 at the upper end of link 74, spaced slightly forwardly of the balance axis 2 of the aileron, the tab T will be drawn or forced downwardly a relatively small distance through another degree or two of downward deflection when 65 the aileron A attains the upwardly-deflected

position of approximately 40°. Such further deflection or change of adjusted position of the tab is, however, immaterial for all practical purposes, and aileron A may be deflected vertically throughout its full range of movement without substantially affecting or interfering with the adjustment of a trim tab T relative to the aileron. The cable drum 77 and the tab adjusting mechanism associated therewith are carried by the aileron hinge arm 4' and aileron A so that the drum and such mechanisms are raised and lowered with the hinge arm and the aileron and, therefore, remain in their positions relative thereto throughout control operation of the aileron, the operating cable 82 permitting such movement of drum 77 relative to the pilot operated mechanism for actuating such drum due to the flexible character of the cable.

If desired, a trim tab may be mounted extending substantially throughout the span of an aileron A, such as the trim tab T' indicated in dotted lines in Fig. 1. Such a full span trim tab T' may be employed without utilizing the aileron A for the purpose of depressing the wing, the aileron being maintained in its neutral position. The area of such full span tab will be such that by deflecting it upwardly, a force sufficient to depress the wing will be developed and the aileron will remain, will in fact be forced and maintained, in its normal, neutral, at-rest position. An adjusting mechanism for an extended or full span trim tab T' can be the same, in all substantial respects, as the adjusting mechanism disclosed and described in connection with the partial span trim tab T.

The up-only aileron type of lateral or roll control system, particularly such a system embodying true up-only ailerons such as in the example here disclosed, has the advantage of permitting of the use of a full-span wing flap of the trailing undersurface type that extends beneath and throughout the span of the up-only ailerons. The use of such a flap is primarily made possible because the up-only ailerons A of the system disclosed are not displaced downwardly from their normal, neutral positions forming portions of the trailing upper surface of the wing. A feature of my invention resides in the novel design, mounting, and operation of a wing flap of the trailing undersurface type and in the combination and structural and aerodynamical association of this design and mounting of flap with ailerons of the up-only type. A flap embodying the features in accordance with my present invention is, however, not restricted to use in combination with ailerons of the up-only type and to use as a full-span flap. The flap presents novel features that produce certain new results and advantages when the flap is used as a partial-span flap in combination with conventional ailerons or other lateral or roll control members.

A flap L designed and mounted for operation in accordance with my invention is disclosed in Fig. 1 of the drawings as a full-span flap extending substantially throughout the span of each of the opposite wings W and beneath the opposite wing up-only ailerons A. In Figs. 4 and 5 the details of the design and mounting of the flap L are shown. The flap L is mounted and forms a portion of the trailing undersurface of the normal contour or air foil section of a wing W when the flap is in its normal raised position, and in such position, the flap L is so associated

with the up-only aileron A thereabove that with the latter in its normal, neutral, at-rest, position, the flap L and the aileron carry out the normal contour of the trailing portion of wing W. In 5 the particular example hereof, the flap L has a chord greater than the chord of an aileron A thereabove, and extends forwardly a distance beyond the leading edge of the aileron. In accordance with the general principles embodied in the 10 mounting and operation of an up-only aileron A of the invention, the flap is also mounted for bodily lowering about a remote hinge axis 83 spaced forwardly a considerable distance from the leading edge of the flap, and is further mounted for rotation about a balance axis 84 that is spaced intermediate the leading and trailing edges of the flap and a distance rearwardly from the leading edge equal to approximately 30% of the chord of the flap in this particular instance. 15 Thus, the portion of the flap forward of the balance axis 84 provides an aerodynamic balance 85 for reaction of the air flow at the underside of the wing thereon to develop forces acting in an upward direction to thereby aid in the rotation of flap L to downwardly-deflected positions about the balance axis 84.

The flap L is mounted on hinge arms 86 extending forwardly therefrom at suitably spaced intervals along the span thereof and these hinge 20 arms extend forwardly to and have pivotal mounting at the hinge axis 83, which axis may be formed in the usual manner by suitable axially bearing pins at the forward ends of the hinge arms. The flap is mounted on the rear ends of the hinge 25 arms 86 by suitable axially-aligned bearing pins that define and provide the balance axis 84 for the flap, such bearing pins being carried by forwardly-extending brackets 87, fixed to the flap spar 88. Any number of hinge arms 86 may be 30 employed for a flap L, the number being determined usually by the size and length of span of a flap L.

In the operation of this flap from its normal raised position, shown in full lines in Fig. 3 of the drawings, and in dotted lines in Fig. 5, the flap is first bodily lowered about the forward remote hinge axis 83 by swinging the hinge arms 86 downwardly. Such a bodily-lowered position of the flap in its initial angular deflection downwardly relative to a wing W, is shown in full lines in Fig. 5. With the flap L in such position, a gap or space G is formed between the flap and the under surface of the wing thereabove, for rearward displacement or flow of air. Following initiation of and during bodily lowering of the flap L about the remote hinge axis 83, the flap is preferably vertically rotated about its balance axis 84 to swing the forward balance portion 85 thereof upwardly and the remaining rearwardly-extending portion of the flap downwardly, so that the flap will assume in its maximum lowered and deflected position, an angle relative to a wing W such that the leading edge of the flap, being the leading edge of the balance portion 85 thereof, is positioned to substantially close any directly forwardly opening and forwardly unobstructed gap between the undersurface of the wing and the leading edge of the flap to thereby, in effect, provide the flap under surface as substantially a downward and rearward continuation of the under surface of the wing in camber-increasing relation therewith. By so positioning the flap in its maximum lowered and angularly deflected positions, its effectiveness in serving as an air brake to retard or check the rate of speed of for-

ward movement of the airplane when it reaches the ground, and the flap has been actuated to such maximum lowered and downwardly-deflected positions, is materially increased. With the flap in substantially its maximum bodily-lowered positions about the remote hinge axis 83 and prior to downward deflection of the flap about the balance axis 84, the substantial gap or space G is provided, between the leading edge and balance portion 85 of the flap and the under surface of the wing W on which mounted, so a substantial flow of air rearwardly between the lowered flap and the under surface of the wing takes place to thereby result in a material reduction of the drag force for the flap at relatively low angles of downward displacement of the flap relative to its normal raised or neutral position. It is also to be noted that with the flap at relatively low angles of downward displacement, and with the wing at relatively high angles of attack, the air flow along the upper surface of the wing tends to break down. The design and mounting of the flap L to provide the substantial gap G as above referred to, will serve to speed up and smooth out the flow of air past the trailing edge of an aileron A mounted above the flap because such flow of air between the wing and flap will tend to draw air down from the stagnant area about the aileron and thus smooth out the flow along the upper surface of the wing and rearwardly across the aileron. Such smoothing out of the air flow over the aileron will tend to make the aileron A more effective for control under conditions when increased aileron effectiveness is highly desirable.

A flap L so designed and mounted, will be most effective for take off and landing of an airplane when the flap is in substantially lowered position of an angular displacement of the order of 10°, such as the lowered position of the flap shown in full lines by Fig. 5 of the drawings, because in this position, the greatest increase of lift may be expected without excessive drag.

Any suitable or desired mechanism may be provided for raising or lowering the flap L about its remote hinge axis 83 and for rotating the flap vertically about its balance axis 84. For example, an arrangement of mechanisms substantially the same as that provided for actuating an up-only aileron A such as disclosed and described hereinbefore, may be utilized. Such mechanisms may include a toggle linkage, as disclosed in Fig. 5, which linkage includes a link or lever 89 coupled pivotally to a flap hinge arm 86 and extending upwardly and pivotally connected to a lower end of a crank arm 90 of a bell crank 91 that has its other crank arm 92 pivotally connected by an actuating rod or link 93 extending forwardly therefrom through the same to horizontally-disposed bell crank 94. The operation of such toggle linkage to bodily raise and lower a flap L about its remote hinge axis 83 will be readily understood, in view of the description of the similar linkage employed with an aileron A. A parallel linkage, similar to that employed in the actuating mechanism for an aileron A may be provided for rotating a flap L about its balance axis 84. For example, such parallel linkage may include a crank arm 95 fixed to and extending upwardly and forwardly from the flap spar 88 and having pivotal connection at its flap end with an actuating rod or link 96 that extends forwardly in parallel relation with a flap hinge arm 86 and that is connected at its forward end to crank arm 97 of a bell crank 98 mounted for rocking

about the remote hinge axis 83 for the flap. Bell crank 97 is actuated from a horizontally-disposed bell crank 99 mounted in the wing forwardly thereof through the medium of an actuating rod or link 100 that extends rearwardly from bell crank 99 to the crank arm 101 of the bell crank 98.

Suitable pilot-actuated mechanisms (not shown) are provided for operating the toggle linkage and the parallel linkage hereinbefore described and comprising the flap actuating mechanisms. In the operation of the flap it is preferable that during lowering of the flap about the remote hinge axis 83 there is simultaneous rotation of the flap about its balance axis 84, although the invention is not limited to such operation. It should be noted though, that in the preferred operation of the flap it is progressively angularly displaced relative to its neutral position and to the wing as the flap is lowered from neutral position to its maximum lowered and maximum deflection about the balance axis 84.

It is also evident that various changes, modifications, additions, eliminations, substitutions and variations might be resorted to without departing from the spirit and scope of my invention and hence, I do not wish to limit myself in all respects to the exact and specific disclosures hereof.

30 What I claim is:

1. In combination, a wing, a control member on said wing adapted for up movement only to control positions, said control member being mounted for translational movement between neutral position disposed within the normal wing contour and a control position bodily raised above and angularly disposed relative to the wing, said control member being progressively angularly displaced during upward movement from neutral 35 position to said control position, said control member also being mounted for rotation about a balance axis intermediate its leading and trailing edges, the portion of the control member forward of said balance axis providing an aerodynamic balance 40 adapted to be exposed to the air flow over the wing substantially throughout the range of upward movement of the control member from neutral position to the aforesaid bodily raised control position, and means for bodily raising said control member and for rotating said control member about said balance axis for upward deflection of said member to positions of increased angular displacement relative to the wing.

2. In combination, a wing, a control member 55 of the type adapted for up movement only to control positions, said control member in neutral position disposed within the normal wing contour and forming a portion of the upper trailing surface of the wing, said control member being mounted for vertical rotation about a balance axis intermediate the leading and trailing edges thereof to angularly deflect said member relative to the wing, said control member being also mounted for bodily movement about a hinge axis spaced forward from the leading edge thereof to position raised from and angularly displaced relative to the wing, the portion of said control member forward of the balance axis providing an aerodynamic balance adapted to be substantially exposed to the air flow over the wing during movement of the control member about said hinge axis to raised position, and said aerodynamic balance portion of the control member adapted to be reacted upon by the air flow over the wing to

develop forces acting about the balance axis to aid upward deflection of the control member about the balance axis to control positions of increased angular displacement relative to the wing.

3. In combination, a wing, a control member on the wing adapted for up movement only to control positions, said control member being mounted for movement between neutral position disposed within the wing normal contour and control positions raised from and angularly displaced relative to the wing, said control member being bodily movable about a hinge axis spaced forwardly of the control member from neutral position to position raised from and angularly displaced relative to the wing, said control member also being vertically rotatable about a balance axis intermediate the leading and trailing edges thereof for vertical rotation of the control member to control positions angularly deflected relative to the wing, and means for bodily raising and angularly displacing said control member about said forward hinge axis and for vertically rotating the control member about the balance axis to positions of increased angular deflection relative to the wing during bodily upward movement of the control member to thereby progressively angularly displace the control member upwardly from neutral position to a control position, the portion of the control member forward of the balance axis forming an aerodynamic balance exposed to the air flow over the wing when the control member is raised from neutral to position above the wing.

4. In an airplane in combination, opposite wings, an aileron of the up-only type on each of said opposite wings, a force means operatively associated with each aileron to continuously apply a force thereto acting to raise the aileron when the aileron is in neutral position, and a pilot operated control system for selectively raising either of said ailerons for control, said control system including means for maintaining that aileron opposite the aileron being selectively raised by operation of the control system against upward displacement from neutral position.

5. In an airplane in combination, opposite wings, a roll control system for said airplane including an aileron of the up-only type on each of said opposite wings, each of said ailerons being rotatable about an axis intermediate its leading and trailing edges to positions upwardly deflected angularly relative to the wing, and also being bodily movable to positions raised from the wing, the portion of each aileron forward of said intermediate axis forming a balance portion adapted to be exposed to the air flow over the wing when the aileron is bodily moved upward to position raised from the wing, to thereby develop forces acting to aid rotation of the aileron to upwardly deflected control positions, and pilot operated mechanisms for selectively moving either of said ailerons upwardly and for angularly deflecting the same about said intermediate axis, said mechanisms including means for maintaining that aileron opposite the aileron being moved upwardly to control positions against upward displacement from neutral position.

6. In combination a wing, an aileron of the up-only type mounted on said wing for movement between neutral position disposed substantially within the normal wing contour and control positions bodily raised from the wing and angularly displaced relative to the wing, said aileron being mounted for bodily raising about a hinge axis

spaced forward therefrom, and for angular deflection about a balance axis intermediate the leading and trailing edges thereof, the portion of the aileron forward of said balance axis providing an aerodynamic balance, actuating mechanism for said aileron including a toggle linkage for bodily raising and upwardly deflecting the aileron about said forwardly spaced hinge axis, and a parallel linkage for rotating said aileron to further angularly deflected positions relative to the wing about said balance axis, and pilot controlled means for operating said aileron actuating mechanism to bodily raise and deflect the aileron about its hinge axis and to vertically rotate the aileron about its balance axis to thereby move the aileron from neutral position to a position of maximum angular deflection about the balance axis.

7. In combination, a wing, an aileron of the up-only type mounted on said wing for movement from neutral position to control positions, said aileron being mounted for movement about a hinge axis spaced forwardly therefrom to position bodily raised above and angularly displaced relative to the wing and being also mounted for rotation about a balance axis intermediate the leading and trailing edges thereof to positions angularly deflected relative to the wing, the portion of the aileron forward of said balance axis providing an aerodynamic balance adapted to be exposed to the air flow over the wing as the aileron is raised bodily about its hinge axis, a pilot actuated control means, and means operatively associating said control means with said aileron whereby said aileron is progressively bodily raised about its hinge axis and angularly deflected about its balance axis to control positions by a single, continuous movement of said pilot actuated control means.

8. In combination, a wing, an aileron of the up-only type mounted thereon, said aileron being movable to position raised bodily from and angularly displaced relative to the wing about a remote hinge axis spaced forwardly from the aileron, said aileron being also mounted for rotation about a balance axis intermediate its leading and trailing edges to further angularly deflect the aileron relative to the wing, and means for raising said aileron about said remote hinge axis and for rotating the aileron about said balance axis to progressively angularly displace the aileron relative to the wing during movement of the aileron from neutral position to maximum angularly deflected control position.

9. In an airplane in combination, opposite wings, a roll control system for said airplane including an aileron of the up-only type on each of said opposite wings, each of said ailerons being rotatable about a balance axis intermediate its leading and trailing edges to positions upwardly deflected angularly relative to the wing, and also being bodily movable about a hinge axis to positions raised from the wing, the portion of each aileron forward of said balance axis forming a balance portion adapted to be exposed to the air flow over the wing when the aileron is bodily moved upward to position raised from the wing, to thereby develop forces acting to aid rotation of the aileron to upwardly deflected control positions, an actuating mechanism for each aileron adapted to bodily raise the aileron about its hinge axis and to rotate the aileron about its balance axis to thereby progressively angularly displace the aileron from neutral position to maximum control position, and pilot operating mechanisms for selectively operating either of said aileron

actuating mechanisms to move the associated aileron upwardly to control positions, said pilot operated mechanisms including means for maintaining that aileron opposite the aileron being moved upwardly to control positions, in neutral at rest position against upward displacement.

10. In combination, a wing, opposite ailerons mounted on said wing for up movement only from neutral position to control positions, and means independently and continuously applying forces to each of said ailerons to raise each aileron from neutral to control positions.

11. In combination, a wing, opposite ailerons mounted on said wing for up movement only from neutral position to control positions raised from the wing, pilot operated control means for selectively raising either of said ailerons from neutral positions, and means independently and continuously applying forces to each of said ailerons acting to raise each aileron from neutral position to control positions upon actuation of the pilot operated control means to raise such aileron.

12. In combination, a wing, opposite ailerons mounted on said wing for up movement only from neutral position to control positions raised from the wing, and means independently and continuously applying forces to each aileron acting to move the aileron upwardly when the aileron is in neutral position.

13. In combination, a wing, an aileron mounted on said wing for up movement only from neutral position on the wing to control positions raised from the wing, and pilot controlled means movable between neutral and control positions, mechanism operatively coupling said means to said aileron for positively moving said aileron between neutral and control positions by movement of said means, and means operatively associated with said aileron applying forces thereto to move the aileron upwardly from neutral to control positions upon movement of said pilot controlled means from its neutral position in the control direction.

14. In combination, a wing, opposite ailerons mounted on said wing of the type having up movement only from normal neutral position on the wing to control positions raised from the wing, a trim tab mounted on each of said ailerons, a pilot controlled mechanism for independently and selectively adjusting each of said trim tabs to positions angularly deflected relative to that aileron on which the adjusted trim tab is mounted.

15. In combination, a wing, opposite upper-surface ailerons mounted on said wing for movement primarily respectively between a neutral position on the wing and control positions upwardly deflected relative to the wing, lateral trim tabs rotatably mounted on said opposite ailerons respectively for vertical angular adjustment relative to said ailerons and to the air flow about the wing, and means for selectively adjusting said lateral trim tabs to cause one of said ailerons to be deflected upwardly to a control position.

16. In combination, a wing, opposite ailerons mounted on said wing for up movement only from normal neutral position on the wing to control positions raised from the wing, a lateral trim tab adjustably mounted on each aileron adapted to be exposed to and reacted upon by the air flow, and pilot controlled mechanism for independently and selectively adjusting a trim tab on one of said ailerons to a position exposed to the air flow such that the reaction of the air flow

thereon causes said aileron to raise to a control position.

17. In an airplane in combination, opposite wings, an aileron mounted on each of said opposite wings for up movement only from normal neutral position to a control position raised from the wing, an adjustable trim tab mounted on each of said up only ailerons, and independent pilot controlled mechanisms for selectively adjusting the trim tabs of said opposite ailerons, respectively.

18. In combination, a wing, an aileron on said wing mounted for up movement only from normal neutral position thereon to control positions raised from the wing, said aileron being located in and having its upper surface forming a part of the trailing portion of the normal upper surface of the wing when the aileron is in normal neutral position, a trim tab mounted in the trailing portion of said aileron and forming a part of the trailing portion of the normal under surface of the wing when the aileron is in normal neutral position, and a pilot controlled mechanism for angularly adjusting the trim tab relative to the aileron and to the wing to cause

20 the trim tab to be acted upon either alternately or cooperatively by the air flow rearward under the wing and the air flow rearward above the wing.

19. In combination, a wing, an aileron on said wing for up movement only from normal neutral position on the wing to control positions raised from the wing, said aileron being located in and having its upper surface forming a part of the trailing portion of the normal upper surface of the wing, a flap member in normal raised position forming a trailing portion of the normal under surface of the wing beneath said aileron, a trim tab mounted in the trailing portion of said aileron, said wing flap being recessed beneath and along the span of said trim tab, said trim tab with the aileron in normal neutral position being received in said recess with the tab under surface forming a part of the trailing portion of the normal under surface of said flap when said flap is in normal neutral position, and a pilot controlled mechanism for vertically deflecting the trim tab to angularly adjusted positions relative to the aileron and wing.

tively coupled to and swingable with said hinge arm and aileron for movement independently of the hinge arm to angularly adjust the trim tab relative to the aileron in any position of the latter.

22. In combination, a wing, an aileron mounted on said wing for up movement only from normal neutral position on the wing to control positions raised from the wing, said aileron being located in and having its upper surface forming a part of the trailing portion of the normal upper surface of the wing and being removed from the lower surface of the wing, wing structure forming a trailing portion of the normal under surface of the wing beneath said aileron, a trim tab mounted in the trailing portion of said aileron, the wing structure beneath said aileron being recessed along the span of said trim tab, said trim tab with the aileron in normal neutral position being received in said wing structure recess with the tab under surface forming a part of the trailing portion of the under surface of the wing, and mechanism for vertically deflecting the trim tab to angularly adjusted position relative to the aileron and the wing in any position of the aileron.

23. In combination, a wing, opposite ailerons on said wing, each of said ailerons being mounted for up movement between neutral, at rest, position on the wing and control positions raised from the wing, pilot control mechanism for selectively raising either of said ailerons from neutral, at rest, position to control positions raised from the wing, and means operatively associated with each of said ailerons for dampening the downward movement of each aileron from control positions raised from the wing into neutral, at rest, position on the wing.

24. In combination, a wing, an aileron on the wing adapted for up movement only to control positions, said aileron being mounted for movement between neutral position disposed substantially within the normal contour of the wing and control positions raised from and angularly deflected relative to the wing about a hinge axis spaced forwardly from the leading edge of the aileron, hinge arms mounted for upward swinging from their forward ends about said hinge axis, the aileron being mounted on and carried by the rear ends of said hinge arms and also being rotatable on said hinge arms independently thereof about a balance axis intermediate the leading and trailing edges of the aileron for vertical rotation to control positions angularly deflected relative to the wing, the portion of the aileron forward of the balance axis forming an aerodynamic balance adapted to be exposed to the air flow over the wing when the aileron is raised from neutral position, a pilot operated control means, an actuating means operatively coupled with a hinge arm for swinging said arm upwardly to bodily raise the aileron about said forward hinge axis, an actuating means for vertically rotating said aileron on the hinge arm about said balance axis to angularly deflect the aileron relative to the wing, and means operatively associating said pilot operated control means with said actuating means for bodily raising and angularly deflecting the aileron about its hinge and balance axes, respectively, whereby said aileron is adapted to be progressively bodily raised about its hinge axis and angularly deflected about its balance axis to control positions by a single, continuous movement of said pilot control means.

25. In combination, a wing, opposite ailerons of the up only type on said wing, each of said ailerons being mounted for rotation about an axis intermediate its leading and trailing edges to angularly deflect the aileron relative to the wing, each aileron being also mounted for swinging about a hinge axis spaced forward from said intermediate axis to bodily raise the aileron from neutral, at rest, position at the wing to control positions bodily raised from and angularly deflected relative to the wing, a pilot controlled mechanism operatively associated with said opposite ailerons for operation to selectively actuate either of said ailerons to swing the selected aileron bodily about its hinge axis to control positions raised from and angularly deflected relative to the wing and to rotate such aileron about its intermediate axis to increase the angular deflection of the aileron relative to the wing.

26. In combination, a wing, a lateral control member mounted on said wing for up-movement only to control positions, said lateral control member being mounted for bodily movement between neutral position disposed substantially within the contour of the wing and control positions bodily raised and angularly deflected relative to the wing and disposed within the air flow over the wing, and a portion of said lateral control member being formed to provide an aerodynamic balance adapted to be exposed to the air flow over the upper surface of the wing substantially throughout the operating range of control positions when said lateral control member is in bodily raised position relative to the wing.

27. In combination, a wing, a lateral control member mounted on said wing for up-movement only to control positions, said lateral control member being mounted for bodily movement between neutral position disposed substantially within the contour of the wing and control positions raised above the wing and disposed within the air flow over the wing, said lateral control member being progressively angularly displaced relative to the wing during displacement between said neutral position and position raised above the wing, and a portion of said lateral control member being formed to provide an aerodynamic balance adapted to be exposed to the air flow over the upper surface of the wing substantially throughout the operating range of control positions when said lateral control member is raised above and progressively angularly displaced relative to the wing.

28. In combination, a wing, a lateral control member mounted in the upper surface of said wing and being movable bodily between a neutral position disposed within the normal wing contour and upwardly deflected control positions raised above said neutral position, said lateral control member being progressively angularly displaced relative to said neutral position during movement from said latter position to upwardly deflected control positions, said lateral control member being also mounted for vertical rotation about an axis disposed span-wise thereof to positions of greater angular displacement relative to said neutral position, and a portion of the lateral control member being formed to provide an aerodynamic balance adapted to be exposed to and reacted upon by the air flow over the wing to develop balancing forces acting in a direction to aid vertical rotation of said lateral control member about said spanwise axis when the said lateral control member is moved up-

wardly bodily from neutral to upwardly deflected control positions.

29. In combination, a wing, a lateral control member forming a portion of the upper surface of the wing when the lateral control member is in neutral position, said lateral control member being mounted for up-movement only from neutral position to upwardly deflected control positions bodily raised above the wing within the air flow over the wing and for progressive angular displacement relative to the wing during said up-movement from neutral position to a control position, said lateral control member being also mounted for vertical rotation about an axis intermediate its leading and trailing edges to control positions of greater angular displacement relative to the wing, and the portion of the lateral control member forward of said intermediate axis providing an aerodynamic balance adapted to be exposed to the air flow above the wing when the lateral control member is moved upwardly from neutral position to thereby develop forces acting on said lateral control member in a direction to aid rotation thereof about said intermediate axis to upwardly deflected control positions, progressively angularly displaced relative to the wing.

30. In combination, a wing, an upper-surface aileron mounted on said wing and in neutral position disposed within the normal contour of the wing, said aileron being mounted for movement upwardly about a hinge axis spaced forwardly of the aileron and for progressive angular displacement of the aileron relative to the wing to upwardly deflected control position in which said aileron is raised above the wing and exposed to the air flow over the wing, said aileron being also mounted for vertical rotation about a balance axis intermediate the leading and trailing edges thereof to control positions of increased angular displacement relative to the wing, the portion of the aileron forward of said balance axis providing an aerodynamic balance adapted to be reacted upon by the air flow over the wing when the aileron is in raised and upwardly deflected control positions, and means for bodily raising and upwardly deflecting the aileron about said hinge axis and for vertically rotating the aileron about its balance axis whereby the aileron may be progressively angularly displaced from neutral position to maximum control position about said hinge and balance axes.

31. In an airplane, in combination, opposite wings, an aileron on each wing mounted for up-movement only and for progressive angular displacement relative to the wing from neutral position disposed within the normal wing contour to upwardly deflected control positions raised relative to the wing, each of said opposite wing ailerons being provided with an aerodynamic balance adapted to be acted upon by the air flow over the upper surface of the wing when the aileron is moved upwardly from neutral position to develop forces acting in a direction to aid up movement of an aileron to control positions, and a control system for selectively actuating either of said ailerons upwardly to control positions, said system including means for maintaining an aileron opposite that aileron being raised to control positions, substantially in its normal neutral position.

32. In combination, a wing, an aileron on the wing adapted for up-movement only to control positions, said aileron being mounted for movement between neutral position disposed within

the normal wing contour and upwardly deflected control positions raised from and for progressive angular displacement relative to the wing about a hinge axis spaced forwardly from the leading edge of the aileron, hinge arms mounted for upward swinging from their forward ends about said hinge axis, the aileron being mounted on and carried by the rear ends of said hinge arms and being vertically rotatable thereon independently thereof about a balance axis intermediate the leading and trailing edges of the aileron for vertical rotation to control positions of greater angular displacement relative to the wing, means operatively coupled with a hinge arm for swinging said arm upwardly to bodily raise and upwardly deflect the aileron about said forward hinge axis, and means for vertically rotating said aileron on the hinge arms about said balance axis to further upwardly deflect the aileron relative to the wing, the portion of the aileron forward of the balance axis forming an aerodynamic balance exposed to the air flow over the wing when the aileron is raised from neutral position.

33. In combination, a wing, and an upper-surface aileron mounted on said wing for translational movement about a hinge axis external thereto and being movable for progressive angular displacement relative to the wing between a neutral position disposed within the normal wing contour and upwardly deflected control positions raised relative to the wing, said aileron being also mounted for rotational movement about a self-contained balance axis, with that portion of the aileron forward of said balance axis constituting an aerodynamic balance adapted to be exposed to and reacted upon by the air flow over the upper surface of the wing when the aileron is moved upwardly from neutral to control positions.

34. In combination, a wing, and an upper-surface aileron mounted on said wing for translational movement about a hinge axis spaced forward thereof and being movable for progressive angular displacement relative to the wing between a neutral position disposed within the normal wing contour and upwardly deflected control positions raised relative to the wing, said aileron being likewise mounted for rotational movement about a movable balance axis disposed within the normal wing contour when the aileron is in neutral position with that portion of the aileron substantially forward of said balance axis constituting an aerodynamic balance adapted to be exposed to and reacted upon by the air flow over the upper surface of the wing when the aileron is moved upwardly to control positions.

35. In combination, a wing, a member disposed spanwise of and forming a trailing portion of the wing, said member being mounted for rotation about a balance axis disposed spanwise intermediate the leading and trailing edges of said member, said member being also mounted for bodily swinging outwardly from and forwardly of the wing about a hinge axis spaced forward from said balance axis about which said member is rotatable, said member in normal inactive position being disposed substantially within the normal wing contour and said member in bodily outwardly and forwardly swung positions being angularly deflected relative to the wing, means for bodily swinging said member outwardly and forwardly from the wing about said hinge axis and for progressively angularly deflecting said member relative to the wing during swinging of said member between said normal inactive

position and said bodily outwardly and forwardly swung positions, the portion of said member forward of said balance axis providing an aerodynamic balance adapted to be exposed in and reacted upon by the air flow about the wing when the member is swung outwardly and forwardly

from the wing to angularly deflected positions relative to the wing, and means for rotating said member about its said balance axis to increase the angular deflection of the member relative to the wing.
